TABULATING MACHINE

Ulrich M. W. Kölz, Berlin, Germany, assignor to
 International Business Machines Corporation,
 New York, N. Y., a corporation of New York

Application January 5, 1935, Serial No. 539
 In Germany January 30, 1934

11 Claims. (Cl. 235—61.7)

This invention relates to accounting machines and more particularly accounting machines of the record controlled tabulator type.

The principal object of the invention is to provide a tabulating machine of improved selectivity of operation and of increased utility with a view to imparting additional operating features as well as improvement in and increased efficiency and utility of the features previously found in such machines.

A more specific object of the invention is to provide a mechanical accounting system which is adapted for the solution of problems peculiar to banking institutions.

Various other objects and advantages of the invention will be obvious from the following particular description of one form of mechanism embodying the invention or from an inspection of the accompanying drawings; and the invention also constitutes certain new and novel features of construction and combination of parts hereinafter set forth and claimed.

In the drawings:

Fig. 1 is a view of the entire machine showing the location of the various units;

Fig. 2 is a section of the card feeding and analyzing mechanism showing the coupling connection therefor. The section is taken substantially along lines 2—2 of Fig. 1;

Fig. 3 is a detail in section taken substantially along lines 3—3 of Fig. 2;

Fig. 4 is a detail of a portion of the read-out mechanism of an accumulator;

Fig. 5 is a central section of an accumulator showing the type of read-out mechanism associated therewith;

Fig. 6 is an isometric view showing the so-called highest order carry mechanism whereby an entry of "one" may be made into the units order under control of the highest order;

Fig. 7 is a central section of the printing mechanism showing the driving instrumentalities;

Fig. 8 is a detail of a so-called double step relay;

Fig. 9 is a further detail of the relay;

Fig. 10 is a view showing the arrangement of the plugboard of the machine through which the various cycles of operation are selectively controlled;

Figs. 11, 11a, 11b, 11c, 11d, and 11e, taken together and placed one below the other in the order named, constitute a wiring diagram of the electric circuits of the machine;

Fig. 12 is a diagram showing the steps in-

volved in carrying out a bank interest problem; Fig. 13 is a portion of a diagram similar to that of Fig. 12;

Fig. 14 is a diagrammatic showing of the manner in which the problem of Fig. 12 is carried out in the machine;

Fig. 15 is a portion of a further diagram similar to that of Fig. 12.

Fig. 16 is a timing diagram of the circuit closing devices.

In order that the detail description may be followed to better advantage, a general statement will be given herein of the operation of the specific embodiment of the invention shown and such will be described as being applied to a problem of a banking institution, but it is understood that the invention may with equal facility be used in many other commercial establishments and in many other relations.

It is the practice in certain banks to prepare a perforated record card for each transaction that takes place between the bank and a customer. Upon such record may be entered the customer's account number, the date of the transaction, the amount, and an indication as to whether the transaction is to be credited or debited to the account. Such cards may be of the form shown in Fig. 14 which illustrates the well known Hollerith type and which usually has twelve index point positions. The nature of the transaction is indicated in the column designated K, a perforation in the 11 index point position indicating a credit card, and its absence denoting a debit card. The cards are arranged according to account number and date and at stated periods are run through the usual Hollerith type printing tabulator to obtain a summation of the various accounts, which is usually the "total amount booked in credit," the "total amount booked in debit" and the "balance in debit" or "credit" as the case may be. In the distribution of interest on these accounts, it has been the practice to obtain the balance for each day's transaction for each account and compute the day's interest thereon, adding the successive interest amounts to obtain the balance of interest payable at the end of the stated period.

In the present arrangement, provision is made to automatically accumulate the sum of all daily balances for the accounting period, which, upon multiplication by the interest rate per diem, will result in the amount of interest for the period.

The operation may best be explained in connection with a specific problem which may be indicated in Fig. 12 of the drawings, which

represents the operations performed in the machine for a group of cards relating to a single customer's account. In this figure, the vertical column labelled "card" indicates the perforations made in the card to represent the transaction date and the amount. Thus, the first card represents a transaction 50 on the first, transaction 25 on the third, and one of 70 on the twentieth. A card representing the thirtieth or closing day of the accounting period is included in the group and this card need not necessarily represent any particular transaction. Its function is to cause the machine to compute the daily balances from the time of the last transaction to the closing day of the accounting period. A fifth card, representing a transaction of 70 and having a day indication of 3, follows the closing card of the account. This card represents transactions which are to be discounted in the calculation of the interest for the accounting period.

On the first line of Fig. 12, the amount 50 is a debit amount and in the operation of the machine, this amount is entered into the debit accumulator #1 and concurrently into the balance accumulator #3. The day number 1 is entered into section I of ACC#6 and at the same time the day number of the next following card, which is 3, is entered into the section II of ACC#6. These entries are indicated along the first line of Fig. 12. Further entries are now suspended and the machine performs a transfer cycle of operations to determine the daily balance.

During this cycle, the amount standing on ACC#2 is complementarily transferred to the balance accumulator #3 and since in this case there is no significant amount standing in ACC#2, the balance in ACC#3 remains 50. This method of balancing involves the transfer of the amount in ACC#2 as a nine complement to ACC#3 and the carry of "1" through the highest order of ACC#3 to the units position whenever the highest order passes from nine to zero. The machine now enters upon a succession of transfer cycles of operation, the number of which is determined by the difference between the day numbers of the first and second cards. During these transfer cycles, the balance standing in ACC#3 is repeatedly transferred to either ACC#4 or ACC#5. If the balance is a debit balance, the amount is transferred to the debit interest ACC#4. If the amount represents a credit balance, the transfer is made to ACC#5. Thus, the balance of 50 is transferred twice to ACC#4 and during each transfer cycle, a "1" is entered into section I of ACC#6, and after two such transfer cycles, the section I of ACC#6 will contain 3, which by comparison with the 3 standing in section II, will cause the termination of the transfer operations and the amounts standing in the several accumulators will be as represented on line 310. The machine then performs a total taking cycle of operations during which ACC#1, 2 and 6 are zeroized. The figures in dotted outline in Fig. 12 along line 310 represent the amounts standing in the accumulators before they are zeroized.

The second record card contains a credit entry of 25 which is entered in ACC#2 while the day number 3 is entered in section I of ACC#6 and at the same time the day number 20 of the following card is entered into section II.

During the following balancing transfer cycle, the complement of the credit amount 25 is entered in ACC#3, resulting in a balance of 25 for the third day. Since there are no transactions

between the third and the twentieth day, this balance of 25 remains unchanged for seventeen days and the machine enters upon a succession of transfer cycles during which the amount 25 is entered seven times and then by denominational order shifting is entered the equivalent of ten times as 250. At the same time, a "1" is entered for each of the first seven transfers and a "10" for the last, at which time the amounts in sections I and II are in agreement and further transferring is interrupted. Line 311 represents the setting of the accumulators at this time. A total taking cycle again clears ACC#1, 2 and 6. The credit transaction of 70 on the twentieth day, when transferred in complementary form to the balance accumulator, results in a credit balance expressed as a complement. During the following transfer cycle, this complementary number is inverted and entered as a true number 450 into the credit interest accumulator #5. The balance is 45 but this is entered as 450 since there are no further transactions between the twentieth and thirtieth days and the balance of 45 does not change for the ten days constituting this interval. Thus, at the end of the accounting period, the amounts standing on the accumulators are as represented on line 312 where 525 is the debit interest figure and 450 is the credit interest figure, each of which, when multiplied by the interest rate per diem, will give the respective amounts of interest.

Where a record card representing an additional transaction beyond the accounting period occurs, the effect is to reduce the debit or credit interest figures. Thus, in the example of Fig. 12, a record card containing a credit amount of 70 and a day number of 3, has its day number entered in section II of ACC#6 while the entry of the day number 30 of the preceding card is suppressed and no entry is made in section I of ACC#6. The balancing cycle again takes place, during which, since no amount is entered from the card of the thirtieth day the balance of 45 is repeatedly entered into ACC#5 resulting in a credit interest figure of 585 as depicted on line 313. The credit amount 70 is now entered in ACC#2 and the day 3 in section I of ACC#6 and balancing again occurs resulting in a credit balance in ACC#3 of 115 which is expressed as a nines complement. This amount is now transferred a number of times equal to the day number, that is, 3, to the credit interest accumulator #5, as a complementary number, the resulting entry being of the tens complement. Following the three transfer cycles, the amounts standing on the accumulators will be as represented on line 314 wherein the credit interest figure has been reduced from 450 to 240 as a result of the last transaction.

It will be appreciated in the foregoing operations that the original credit interest figure of 450 has been increased by 3 times 45 as on line 313 and is then decreased by 3 times 115 giving a final figure of 240, line 314, which is the original figure 450 minus 3 times 70.

Fig. 13 shows the manner in which the debit interest figure 525 is reduced in response to a transaction card following the closing card in which the amount involved is a debit amount. In this case, the balance resulting in ACC#3 is a credit balance of 45 and for the three transfer cycles following the balancing operation, the credit balance is transferred in the form of a complement to the credit interest accumulator #5. Following this and after the amount 70 has

been entered in ACC#3, the resulting balance of 24 is repeatedly entered in complementary form in ACC#4. This has the effect of repeatedly subtracting the balance of 24 so that the final interest figure is 453 representing the original debit balance of 525 minus 3 times the amount 24. Fig. 15 shows the manner in which a debit interest figure 1215 is reduced in response to a transaction card following the closing card in which the amount involved is a debit amount and the daily balance in ACC#3 is a debit balance of 100. In this case, the day number of the card following the closing card is 13 and during the transfer cycles following, the debit balance of 100 is transferred as a true number to ACC#4 to increase the amount therein by 13 times 100. Following this and after the amount 50 has been entered in ACC#3 the resulting balance of 150 is repeatedly entered in complementary form in ACC#4. This has the effect of repeatedly subtracting the balance of 150 so that the final interest figure is 565 representing the original debit balance of 1215 minus 13 times the amount 50.

General description

The separate units of the machine will first be described in sufficient detail for an understanding of their construction and their manner of operation. Following this, the circuit diagram will be explained and the complete operation of the entire machine set forth.

The mechanical structure of the machine is substantially similar to that shown in Patent No. 1,976,617 to C. D. Lake and G. F. Daly, granted October 9, 1934. In this patent (Figs. 2 and 3) is shown the usual card feeding, sensing and stacking mechanism and drive therefor which has been modified as shown in Fig. 2 of the present application to provide for declutching of the card feeding mechanism from the main drive. Fig. 4 of the patent shows the usual accumulating mechanism including direct subtraction devices which are not employed in the present machine and need not be used in the patent if so desired. The patent differs in the design of the well known readout device of the accumulator and the present design is as shown in Fig. 5 of the application. Also, the usual elusive one devices of the patent (Fig. 5 thereof) are modified as in Fig. 6 of this application for less flexibility of operation than in the patent. Fig. 7 of the patent shows the accumulator drive and reset gearing and Fig. 8 shows the well known zero button magnet used for selective reset of the accumulator. Fig. 23 of the patent shows the main clutch of the machine and its operating magnet while Fig. 9 shows the reset clutch and its operating magnet and associated mechanisms together with the reset motor. Figs. 10, 11 and 12 of the patent show the printing mechanism and its controls which are also shown in Fig. 7 herein, wherein many of the parts are of different design but perform the same functions as similar parts in the patent. Fig. 1 of the patent shows the general arrangement of the machine and corresponds to Fig. 1 herein with the card feeding mechanism at one end, the printing mechanism at the other and the accumulators in between. For greater accumulator capacity in the present case, three additional accumulators are provided which are mounted above the five usual accumulators and driven in the same manner through well-known intermediate gearing such as shown in the patent to Lake and Storey No. 1,775,132 in Figs. 5 and 9 thereof.

The mechanical structure of the present machine is furthermore exactly the same as that of the machine of my Patent No. 2,131,226, granted September 27, 1938, which is known as the "Hollerith Tabulating Machine Type BK" manufactured by the "Deutsche Hollerith Maschinen Gesellschaft m. b. H." of Berlin, Germany. The present invention is directed to improvements in the electrical controls of such machine and an understanding thereof requires a knowledge of said commercial machine and its manner of operation. Only sufficient structure will therefore be herein described to point out wherein departure has been made from previous arrangements.

The main operating circuits and electrical wiring arrangement are substantially the same as disclosed in my copending application Serial No. 729,385, filed June 7, 1934, now Patent No. 2,131,226, granted Sept. 27, 1938, and the operating circuits in the present case will therefore be described in only so much detail as is necessary for an understanding of the present invention.

Referring to Fig. 1, the machine comprises, generally, a card feeding and analyzing section at the left end thereof which feeds the record cards to the analyzing devices where they are sensed by the analyzing mechanism. The accumulating mechanism is located in the center of the machine and comprises eight accumulators.

A clutching mechanism is provided intermediate the card feeding and accumulating sections whereby the two may be disconnected so that the accumulators may be operated without accompanying functioning of the card feeding devices.

The printing mechanism is located at the right end of the machine and includes seven so-called banks of printing type bars. Below the accumulators is the plugboard of the machine by means of which the various units may be coordinated to produce the desired result in the form of a printed record. The tabulating motor, indicated at TM, serves to drive the card feeding devices, the accumulators, and the printing mechanism through suitable controlling mechanism, which will be described hereinafter.

Card feeding mechanism

The card feeding mechanism and its de-clutching device are shown in Figs. 2 and 3 where the pulley 10, driven from motor TM, has driving connection with shaft 11, which, through gears 12, drives a shaft 13. The latter in turn, through gears 14, drives the accumulator drive shaft 15. The usual clutch connection is provided between pulley 10 and shaft 11, which clutch connection is controlled by a clutch magnet 99 shown in the circuit diagram Fig. 11. The mechanical structure of this clutch is as shown in Fig. 23 of Patent No. 1,976,617.

This shaft 15 is in constant rotation as long as shaft 11 is driven by the motor. One of the gears 14 engages a gear 16 (Fig. 3) to which is secured a clutch driving element 17. Adapted to cooperate with element 17 is a spring-pressed dog 18 carried by a member 19 integral with a gear 20, which latter has connection to the usual train of gears which serve to convey the record cards through the analyzing devices. The dog 18 is normally held out of engagement with element 17 by a clutch releasing arm 21, which, upon energization of a magnet 22, is rocked in a clockwise direction to release dog 18 for engagement with element 17 so that the card feeding mechanism may operate. During its operation, the

cards are fed singly from a stack 23 by means of a picker 24 to suitable rollers which convey the cards past upper analyzing brushes UB and lower analyzing brushes LB.

The brushes are so spaced that a record card feeds past the lower analyzing brushes LB exactly one machine cycle after it has passed beneath the upper analyzing brushes UB. It will be apparent that card feeding operations only take place when magnet 22 is energized to permit coupling of the card feeding mechanism to the driving mechanism.

Accumulators

As the perforated cards pass the lower brushes LB perforations in their index points permit instantaneous closure of circuits through the proper lower analyzing brushes LB to energize accumulator magnets 25 (Fig. 5). As usual, the timed energizations of these magnets control mechanism for entering the data corresponding to the card reading on the wheels 26.

The wheels 26 are driven from a clutch shaft 27 to which a gear 28 is coupled upon energization of magnet 25. Gear 28 has driving connection with wheel 26 through a gear 29 fast upon the wheel. Gear 28 also drives a gear 30 upon which is mounted a yoke 31 (see also Fig. 4). Slidably mounted on the yoke is a pair of contact plungers 32 urged outwardly by a looped leaf spring 33. One of the plungers 32 cooperates with an arcuate conductor 34 while the other plunger cooperates with a plurality of segments 35 which correspond in number and position to the several digit indicating positions of the wheel 26. The relationship between the several parts is such that the contact plungers 32 are angularly displaced according to the reading on the accumulator wheel. Thus, when the wheel is set to represent "5", one of the plungers 32 will be in contact with the "5" segment 35 and the other plunger will be in contact with the conductor 34. Each group of segments 35 corresponding to the same digit constitutes a common bar of conducting material mounted at its ends upon a suitable insulating block 36.

Associated with each accumulator wheel is the usual carry lever 37 (Fig. 5) which controls carrying from its order to the next higher. As any wheel passes from "9" to "0" its lever 37 is rocked slightly clockwise and thereby conditions the next higher order to receive an additional unit during the carrying period of the machine cycle.

Highest order carry mechanism.—In Fig. 6 there is shown mechanism for connecting the highest order carry lever 37 with the lowest or units order carry lever in such manner that when the highest order wheel 26 passes from "9" to "0", the lowest order lever 37 will be rocked slightly clockwise and an additional unit will consequently be entered into such order.

This mechanism comprises a lever 38 having an adjustable arm 39 at one end disposed in the path of the highest order lever 37. The opposite end of lever 38 has connection with an arm of a member 40, the other of whose arms engages an angle 41 secured to the units carry lever 37 so that as the arm 39 moves downwardly the angle 41 will be moved in the same direction to also draw the units lever 37 down. This carry lever controlling mechanism is contained in each of the eight accumulators and functions during subtracting operations of the machine as will be further explained hereinafter. Tripping of the highest order lever 37 when the wheel 26 passes

from "9" to "0" will release its associated latch 37a so that the latter may rock in a clockwise direction and cause closure of a pair of contacts 160. These contacts function to condition the read-out circuits of the accumulator as will be explained.

Printing mechanism

The printing mechanism is shown in Fig. 7 and is similar to that shown in the Lake and Daly patent mentioned above. The type bar 42 is positioned relatively to the platen 43 to bring the proper type 44 into printing position opposite the platen. The "total" shaft 45 driven by the reset motor RM is provided with a cam 46 cooperating with a roller 47 carried on arm 48 which is freely rotatable on shaft 49. As the cam rotates, arm 48 rocks clockwise and a lug 50 on arm 48 cooperating with a double-armed member 51 fixed to shaft 49 also rocks the member clockwise. Arm 52 secured to shaft 49 is linked to printing crosshead 53 which serves to raise the type bars 42 in synchronism with the total taking operation so that the type 44 successively pass printing position opposite the platen.

Owing to spring operated scissors connections 54, however, the type bars 42 may be arrested at any printing position without interfering with the upward movement of the crosshead 53. The type bars are arrested under control of the printing magnets 55. When any such magnet is energized it attracts its armature 56 and pulls a call wire 57 toward the right thereby releasing a latch member 58 normally holding a stop pawl 59. When the pawl 59 is so released, it is spring operated to engage ratchet teeth 60 formed on the type bar 42 to prevent further upward movement of the bar and thus hold a particular type 44 in printing position.

During listing operations, shaft 49 is rocked to reciprocate printing crosshead 53 under control of listing cam 61 carried by list shaft 62 which is operated from the motor TM through shaft 15 (Fig. 2) in the usual manner during listing and card feeding operations.

Cam 61 is provided with a cam slot which cooperates with follower roller 63 carried by an arm 64 loosely mounted on shaft 49. A lug 65 on arm 64 cooperates with double-armed member 51 to rock shaft 49. The configuration of the cam groove is such that the type bars are elevated and the type 44 move past printing position in synchronism with the passage of the corresponding index point positions in the record cards past the analyzing brushes. Cam 61 is freely mounted on shaft 62 and may be coupled thereto under control of a magnet 66 which, upon energization, will rock its armature 67 which in turn through an extension 68 will rock an arm 69 carried by a rod 70. Rod 70 also carries an arm 71 whose free end is adapted to engage the pin 72 in clutch releasing arm 73 which normally engages a spring-pressed dog 74 integral with the cam 61.

Rocking of arm 73 under the influence of magnet 66 will free dog 74 for engagement with clutch driving element 75 secured upon shaft 62 so that the cam 61 will move with the shaft. Magnet 66 is energized whenever listing operations are to be performed. The cam 61 is adapted to cooperate with a roller 76 in an arm 77 which is freely mounted on the supporting rod of arm 73 and will rock the arm clockwise to cause opening of a pair of contacts 78 whose function will be explained in connection with the circuit diagram.

The adding and printing mechanisms just de-

scribed are well known in the art and only sufficient thereof has been explained for an understanding of the present invention.

Double step relay

A double step relay is illustrated in Figs. 8 and 9 whose function is to control the reading out circuits of the accumulator for balance printing when subtracting operations are being performed. The relay comprises a magnet 79, which, upon energization, will rock its armature 80 secured to a pivoted rod 81. Rod 81 also carries an arm 82 at the free end of which is pivoted a pawl 83 spring-pressed into engagement with a ratchet 84 which has ten teeth. A spring-pressed pivoted member 85 serves as a detent to hold ratchet 84 in position. Rocking of rod 81 will elevate pawl 83 and upon deenergization of magnet 79, spring 82a will return member 84 to advance ratchet 84 one tooth. The ratchet is secured upon a rod 86 which has secured thereto a cam 87 of pentagonal outline. Cooperating with cam 87 are contacts 79e and 79b which are adapted to open and close respectively when the high points of the cam lie directly above rod 86.

Since ratchet 84 has ten teeth and cam 87 has five low points and five high points, it is obvious that a single operation of magnet 79 will open contacts 79e and close contacts 79b and a second energization will permit them to resume the position they occupy in Fig. 9. The function of contacts 79e and 79b will be more fully explained in connection with the circuit diagram.

Wiring diagram—operating circuits

The various mechanical devices employed in the present invention have now been explained to show their manner of operation. The wiring diagram, which is about to be explained, will serve to show how the several elements are co-ordinated in the operation of the machine and it will be pointed out in connection with this explanation how various relationships may be obtained through the use of the plugboard of Fig. 10. The electric circuits are shown in Figs. 11, 11a, 11b, 11c, 11d, and 11e, which, taken together and placed one below the other in the order named, constitute a complete wiring diagram of the electric circuits of the machine.

In the circuit diagram relay magnets and their associated contacts have generally been shown in close proximity to one another and the related contacts have been designated with the same reference numeral as the controlling magnet with a lower case letter suffixed thereto. In certain instances, where it would add to the complexity of the circuit connections to show the relay magnets and their contacts together, the magnet has been shown in dotted outline adjacent to the contacts which it controls.

The various cam controlled contacts, as shown on the drawings, are suitably labelled to indicate the units with which they are associated. Thus, cam contacts prefixed "T" are those which operate when the card feeding mechanism functions and their location is indicated in Fig. 2 where contacts T11 are shown. Contacts prefixed "L" and "ZL" function when the tabulating and listing mechanisms operate (i. e. whenever the motor TM is in operation) and those which operate only during total taking operations are prefixed with the letter "P" or "SP." The cams for operating contacts L and ZL are driven in the usual manner and are mounted on a shaft corresponding to shaft 291 in Fig. 7 of Patent No. 1,976,617.

The cams for operating contacts P and SP are also driven in the usual manner and are mounted on a shaft corresponding to 166 in Fig. 15 of Patent No. 1,976,617 which is shaft 45 in the present application.

In order to facilitate the location of the various electrical devices on the circuit diagram, vertical broken lines are drawn at the sides thereof with spaced graduations, the spaces between which are serially numbered. In the following description the various elements will be located with reference to these numerals. For example, a cam contact, such as P1, will be designated as being located at (L3) on the circuit diagram. The designation L3 is interpreted as left of section 3. Elements in the center of the drawing will be designated as C for center followed by the appropriate numeral, and elements at the right will be designated as R.

Figs. 11, 11a, 11b, 11c and 11d of the wiring diagram correspond substantially to the similarly identified figures in my Patent No. 2,131,226, and in order that cross referencing may be facilitated the same reference characters are herein employed so that, where parts of the circuit shown are not specifically described and are not directly involved in an understanding of the invention, an explanation of their operation may nevertheless be readily had. Fig. 11e of the diagram shows the electrical devices which are employed to effect a modification of the circuits of the prior machine, and the manner in which this is done will be set forth more particularly hereinafter.

Initial resetting circuit.—As is customary in tabulating machines of this type, an initial resetting cycle of operation is usually performed to insure that all accumulators are zeroized and to prepare the usual automatic group control mechanism for proper functioning. Referring now to Fig. 11, after the main line switch has been closed, current will be supplied to left side of line 90 and right side of line 91. Depression of the reset key at this time will close contacts 92 (C5) to establish a circuit traceable as follows: from left side of line 90, cam contacts L5 (L7), contacts P3, reset clutch magnet 93, relay magnet 94, relay contacts 95d, reset key contacts 92, switch S22b, switch S3c, switches S18a, S20a, contacts 97a, to line 91.

The relay 94 closes its contacts 94a (C1) to complete the circuit through the reset motor RM. This circuit follows from line 90, contacts L5, motor RM, contacts 94a, to line 91, and the total shaft 45 (Fig. 7) consequently commences rotation during which cam contacts P4 (R1) are closed to short circuit the contacts 94a and maintain the motor circuit throughout the cycle.

During the cycle contacts P3 (L7) open to interrupt the reset clutch circuit. Also during this cycle the operation of cam contacts P5, P6 and P7 (L11—12) sets up the automatic control circuits which will be more fully explained later under the heading "Control setup circuits." The setting up of these circuits will effect energization of the so-called motor control relay magnet 87 (L12) to cause opening of contacts 97a (R4) and closure of contacts 97b. These contacts will thereafter remain in their shifted position until the group control mechanism detects a change in group control designations on successively analyzed record cards.

The machine may now commence card feeding operations and these may be initiated by depressing the start key to close contacts 98 (C3) whereupon a circuit will be completed as follows: from

left side of line 80, cam contacts P1, (L3) clutch magnet 99, contacts 99a, relay coils 100, 95, a pair of stop key contacts 101, start key contacts 98, a second pair of stop key contacts 102, contacts 103a of intermediate control relay 103 (energized as explained later under "Control setup circuits"), contacts 97b of minor control relay 97 (now closed), to line 91. Energization of clutch magnet 99 will cause opening of related contacts 99a and consequently relay magnet 104 will be included in the circuit. This relay will close its contacts 104a (C2) thereby completing a circuit through the tabulating motor TM.

The energization of clutch magnet 99 will cause operation of the accumulating mechanism by effecting a clutch connection in the usual manner between pulley 10 and shaft 11 of Fig. 2 and energization of the printing clutch magnet 86 (C4) will cause accompanying operation of the printing mechanism.

Printing clutch circuit.—The circuit for magnet 86 is traceable from line 80, magnet 86 (C4) upper contacts P11, contacts 97c (closed during the initial resetting cycle by magnet 97), to line 91. With the magnet 86 energized, printing operations will take place during each cycle of operations of the machine.

Relay magnet 95 (C3), energized upon completion of the circuit through clutch magnet 99, will close its contacts 95a to transfer the circuit through the clutch magnet to the control of cam contacts L2 which hold the circuit throughout the cycle.

Card lever circuits.—As the record cards feed downwardly past the analyzing brushes UB the card lever contacts 109 (R12) close to energize relay magnet UCL whose contacts UCLa form a holding circuit through cam contacts L13. Another pair of contacts UCLb (C3) in the circuit of clutch magnet 99 short circuits cam contacts L2 and L3 to maintain the motor circuit when these cam contacts open momentarily during the cycle. As the card passes the lower analyzing brushes LB, lower card lever contacts 110 (R12) are closed to energize lower card lever relay LCL whose contacts LCLa provide a holding circuit through cam contacts L14. Relay LCL controls several contacts which will be explained in connection with the circuits which they control. Card lever contacts 109 and 110 correspond to the usual card lever contacts 58 and 59 respectively of Patent No. 1,976,617 and their location and manner of operation by the cards is shown in Figs. 2 and 2a of that patent.

Card feed clutch circuit.—For card feeding operations, where a card is to be fed for each so-called accumulating cycle, the switch S3a (L4) is in its full line position and a circuit completed from line 90, through card feed clutch magnet 22 (L4), switch S3a, to line 91.

Switch S3a is set in its full line position when the machine is used for ordinary tabulating operations in which no so-called transfer operations are involved, and card feeding therefore takes place whenever the motor TM is coupled to the drive shaft 11.

Under control of the circuits thus far described the machine will operate to feed cards successively through the analyzing mechanism and circuits will be completed through perforations in the records for controlling the operation of the accumulating and printing magnets. The detailed tracing of the accumulating and printing circuits will be deferred until later in the description under the heading "Adding and print-

ing circuits." During the feeding of the cards, the automatic control mechanism, generally designated GC in (C11), functions to keep the machine running as long as successive cards contain the same group control number.

Upon detection by this mechanism of a change in group control designation, the relay magnet 97 (L12) will become deenergized, causing opening of the related contacts 97b (R4) to interrupt the circuit through main clutch magnet 99, which in turn will break the circuit to the motor TM and card feeding and accumulating operations will thereupon cease.

Automatic resetting circuits.—If switch S2 (R6) is closed, the closure of cam contacts L6 toward the end of the last adding cycle when contacts 97a are closed will complete a circuit to initiate automatic resetting operations. This circuit is traceable from line 80, contacts L5, P3 (L1), reset clutch magnet 93, relay magnet 84, contacts 95d, switch S2, contacts L6, switch S22b, switch S3c, switches S18a, S20a, contacts 97a, to line 91. Energization of magnet 93 will cause a resetting cycle of operations of the machine during which the amounts standing in the accumulators will be printed and the group control devices again set up to open contacts 97a.

If switch S22b is open, the circuit will include relay contacts 300c (introduced for the purposes of the present invention) and will remain incomplete until these contacts close in a manner to be set forth hereinafter under the heading "Entering '100' in section I of accumulator 6." It may be pointed out at this time that the switches S22a and S22b are operated together by a common connection so that, if one is closed, the other is open and vice versa.

Automatic restarting circuit.—Following the reset cycle the machine may automatically enter upon card feeding and analyzing operations, if switch S1 (C4) is closed. Under such condition the closure of cam contacts P2 near the end of the reset cycle will complete the circuit to the main clutch magnet 99 through the following path: from line 80, contacts P1 (L3), magnets 89, 104, 100, and 95, stop key contacts 101, switch S1, contacts P2, contacts LCLc (closed if there is a card at the lower brushes), contacts 103a, contacts 97b, to line 91. The energization of magnet 99 will, as explained above, cause the machine to enter upon a tabulating cycle of operations during which the succeeding record cards are analyzed and the data thereon entered into the recording devices.

Automatic control circuits.—The automatic group control circuits which keep the machine in operation as long as classification data on successively analyzed cards are the same will now be explained in as much detail as is necessary for an understanding of the present invention.

A number of double-wound relay magnets are provided each having a pick-up winding 112 (R10) and a holding winding 113 shown separately in Fig. 11a. Windings 112 terminate in the plugboard sockets 114 and 115 (see also Fig. 10) through which the windings may be plug connected in series with the brushes UB and LB. Since the index point positions on the card passing the lower brushes are analyzed concurrently with the analysis of the corresponding index point positions of the following card passing the upper brushes, a perforation occurring in any index point position of both cards will complete a circuit at a time in the cycle of the machine corresponding to the location of the perforation.

The circuit is traceable as follows: from line 90, through wire 116 (L13), cam contacts L7, upper brush contact roller, brush UB, plug socket 117, plug connection 118 to socket 114, winding 112, socket 115, plug connection 119, to lower brush socket 120 (R31) (see also plugboard Fig. 10), lower brush LB, wire 121, impulse distributor 122 (R25), wire 123, lower card lever relay contacts LCLD (R4), contacts 103a and 97b, to line 91. On the plug board (Fig. 10) representative connections are made for controlling on columns 1 to 5. Energization of winding 112 will close its related contacts 112a (R10) and 112b (C10), the former setting up a holding circuit for the winding 113 which is traceable from line 91 (R11), through winding 113, contacts 112a, cam contacts L11 to line 90 through wire 116. Contacts L11 hold the windings 113 energized until the end of the cycle and until the mechanism has performed its controlling functions.

It is thus apparent that the windings 112 are differentially energized in accordance with the value of the controlling perforation and that the windings 113 hold all the selected circuits to keep contacts 112b closed in positions in which agreement occurred between the cards. In the machine there are provided sixteen sets of windings 112, 113. On the circuit diagram, however, only three are shown to avoid undue repetition of similar parts.

After all the index point positions have been analyzed, the machine tests the setting of the contacts 112b. If there was agreement in all the control columns, the contacts 112b corresponding to those columns will be closed and a series circuit will be traceable through each such contact.

The contacts associated with the so-called "minor" controlling field of the record card will be grouped together and a connection 124 (C12) made between the plug socket 125 of the last position and "minor" plug socket 126. This places the first two contacts 112b (C12) in the minor holding circuit. A plug connection 127 made between another plug socket 125 and a socket 128 will place the next two contacts 112b in the intermediate holding circuit and a plug connection 129 made to a socket 130 will place the fifth and sixth contacts 112b in the major holding circuit. The ultimate object of the group control mechanism is to keep the motor control relay 97 energized, if there is agreement in the minor, intermediate and major control fields and to cause deenergization of magnet 97, if there is a break or disagreement in any of these fields.

Minor holding circuit.—Magnet 97 is normally held energized through a circuit set up during the initial reset cycle of the machine. During this cycle, cam contacts P7 (L12) close, completing a circuit from line 90, switch S12 (L12), contacts P7, magnet 97, contacts L8 (C12), L9 (C11), contacts L10, (C10), wire 131, to line 91. Magnet 97 closes a pair of contacts 97d (L12) to establish a holding circuit through the magnet. This circuit is called the minor holding circuit and remains established as long as classification data on the record cards do not change.

Intermediate holding circuit.—Concurrently with the setting up of the minor holding circuit the intermediate holding circuit is also completed upon closure of cam contacts P6 provided switch S14b (L12) is closed. This circuit is traceable from line 90, switch S12, switch S14b, cam contacts P6, intermediate control relay 103, contacts L9, L10 to line 91 through wire 131. Magnet 103 will close contacts 103b to provide a holding cir-

cuit which is called the intermediate holding circuit which remains energized as long as intermediate classification data do not change.

Major holding circuit.—In a similar manner the major holding circuit is established upon closure of cam contacts P5. This circuit is traceable from line 90 (L12), switches S12, S14b, contacts P5, major control relay 132, wire 133, contacts L10, to line 91. Relay 132 will close its contacts 132a to provide a holding circuit for the relay which is known as the major holding circuit and this remains energized as long as major classification data do not change.

If there is a change in the minor group number, the minor holding circuit alone is broken. If there is a change in an intermediate group number, both the minor and the intermediate group circuits are broken, and if there is a change in the major group number, the minor and intermediate circuits are also broken. This provides against the possibility of the major number changing and the intermediate and minor group numbers remaining the same, which would preserve the control circuit to magnet 97.

During each cycle of the machine, cam contacts L8, L9, and L10 (C12) open momentarily. Since these contacts are in the minor, intermediate, and major holding circuits respectively, these circuits would be interrupted at this time, if no other path were provided around the contacts.

Minor shunt circuit.—During tabulating and listing cycles of the machine the contacts 112b provide a shunt circuit around contacts L8, L9 and L10. For example, the first six contacts 112b, when all are closed and when plug connection 124 is made as shown, short circuit contacts L8, L9 and L10, the short circuit running from the lower blade of contacts L8 (C12) to the lowermost contacts 112b, then to the upper blade of the sixth pair, plug connection 129, contacts UCLc, wire 131, to line 91.

Intermediate shunt circuit.—The intermediate shunt circuit comprises the four contacts 112b associated with both the major and intermediate controlling fields of the card and short circuits contacts L9 and L10, the short circuit extending from the lower blade of contacts L8, wire 134, serially through the contacts 112b, 3 to 6, plug connection 129, contacts UCLc, wire 131, to line 91. Thus, if at the time contacts L9 and L10 open and the control relays have registered agreement between the two cards analyzed the intermediate holding circuit will be sustained through the four contacts 112b, 3 to 6.

Major shunt circuit.—The major shunt circuit comprises two uppermost pair of contacts 112b used for controlling and short circuits the contacts L10, the short circuit extending from lower blade of contacts L10 through wire 135, socket 128, plug connection 127, the upper two pairs of contacts 112b (5 and 6) through plug connection 129, relay contacts UCLc which are closed while cards are passing the upper brushes, to wire 131, and line 91.

Thus, if at the time contacts L8, L9, and L10 open and the control relays have registered agreement, the three holding circuits will be sustained through the contacts 112b. If at such time one of the two lowest contacts 112b failed to close, the minor holding circuit would have been broken, deenergizing relay magnet 97, causing stoppage of the machine or automatic entry upon a total taking and resetting cycle. If either of the contacts 112b in the intermediate pair had failed to

close, both the intermediate and minor holding circuits would have failed to remain energized and the intermediate control relay 103 would also have been deenergized and similarly, if either of the major contacts had failed to close, the major control relay 132 would in addition have been deenergized.

Control setup circuits.—During the subsequent total taking cycles, closure of cam contacts P5, P6, and P7 will again establish the several holding circuits and comparison of the successively fed records of the next group will take place and card feeding will proceed until there is again a break in one of the circuits. Switches S6, S7, and S8 are provided (C10, C11 and C12) which, when in their closed or full line positions, permanently short circuit the contacts L10, L9, and L8 respectively, to render the related sections of the control inoperative. If all are closed, the holding circuits remain established indefinitely.

Several card lever relay contacts are included in the control holding circuits to maintain them at the beginning of the tabulating machine operations until cards have been advanced to the analyzing brushes. Thus, card lever relay contacts UCLd (C10) and LCLe (C12) are normally closed and connected in series so as to short circuit all the contacts 112b.

This short circuit will be maintained until cards are at the upper brushes when contacts UCLd are opened. Also, relay contacts LCLf and UCLf (C11) maintain the intermediate holding circuit until cards are at the two sets of brushes and contacts LCLg and UCLg (C10) perform a similar function.

The machine is arranged so that the three holding circuits may be set up concurrently and the machine will perform a single reset cycle or the machine may perform two reset cycles during the first of which only the minor relay is set up and during the second the intermediate and major relays are concurrently set up. For the single reset cycle condition, switch S14b (L12) is closed so that a circuit is completed therethrough to the cam contacts P5, P6 and P7 during the same cycle through circuits which have been traced above in connection with the several control holding circuits. For successive reset operations the switch S14b is moved to its open or dotted line position so that during the first reset cycle only relay 97 will be energized through switch S12 and cam contacts P1. The contacts P5 and P6 which control the setting up of the intermediate and major relays are timed to close and again open before contacts P7 close and in series with contacts P5 and P6 are relay contacts 97f, which close upon energization of relay 97 after P5 and P6 have opened. Thus, after relay 97 is energized during one reset cycle and closes its contacts 97f, the contacts P5 and P6 will become effective in the following reset cycle to energize both relays 103 and 132 through the closed contacts 97f.

The closing of contacts 97b (R4), due to the setting up of a minor control circuit, will not complete the tabulating motor circuit since in series with contacts 97b are contacts 103a which are still open due to the non-completion of the intermediate control circuit.

At L6 is a switch S13a which is closed for the successive reset operations. This switch is connected through a normally closed switch S9b with contacts 103f which are closed at this time so that opening of cam contacts P3 during the first reset cycle will not interrupt the reset clutch circuit since contacts 103f and switches S9b and

S13a short circuit the contacts and initiate a second reset cycle.

During this cycle the intermediate and major control relays 103 and 132 are set up through a circuit extending from line 90 (L12), switch S12, contacts 97f, now closed, thence in parallel through contacts P5 and P6 and control relay magnets 132 and 103. Energization of magnet 103 will close its contacts 103a (R4) to re-establish the tabulating motor circuit and contacts 103f (L1) will be open so that the reset clutch magnet circuit may be interrupted during the second reset cycle upon opening of contacts P3.

Zero button magnet circuits.—In Fig. 1 are shown the so-called zero button magnets 157 of which there is one for each accumulator. These magnets in the usual manner, when energized, couple the accumulators to the reset mechanism for resetting or zeroizing of the accumulators. These magnets are shown in the circuit diagram in Fig. 11 at C8 where each is wired to a plug socket E-1, E-2, etc., for individual selection. These sockets may be suitably plug connected to one of a trio of sockets C-1, C-2, or C-3 (L8) by suitable plug connections such as 161, Fig. 10.

In the upper right hand section of the plug-board (Fig. 10) are vertical columns of plug sockets labelled A-X and the horizontal rows formed by these columns are numbered 1-8. For convenience in referring to particular sockets they will be referred to and designated by the ordinates A-X and 1-8. For example, the socket E-1 is the first socket in column E; C-2 is the second socket in column C, and so on.

Connection to the socket C-1 will condition the selected accumulator for resetting upon a minor group change. Connection to the middle socket C-2 will cause resetting on an intermediate change and connection to the lowest C-3 socket will condition the selected accumulator for resetting on a major change. The connection 161, such as in Fig. 10, will select the accumulator for resetting on a minor change. If more than one accumulator is to be affected, parallel plug connections 162 may be made between sockets E-1, E-2, etc. Thus, for the plugging example shown, the accumulators associated with the three sockets E-1, E-2 and E-6 will be reset upon a minor group change.

Single cycle resetting.—When the machine is conditioned for concurrent resetting, all connected zero button magnets 157 will be energized during the single reset cycle, if there has been a major group change, deenergizing relays 132, 103 and 97. This is brought about as follows: A circuit is completed from line 90 (L12), through switch S11a, wire 163, to minor socket C-1 (L8) and thence through plug connection to socket E-1, zero button magnet 157, cam contacts P8 (C9), to right side of line 91.

A parallel circuit will be completed from switch S11a through contacts 103c (L11), switch S14a, relay magnet 164, cam contacts P8, to line 91. Magnet 164 will close its contacts 164a to provide a holding circuit from switch S11a, wire 163, contacts 164a, magnet 164, contacts P8, to line 91. This circuit will also branch at contacts 164a to magnet 341 and intermediate plug socket C-2 and thence through the associated zero button magnet 157 to line as before. Similarly, a relay magnet 165 associated with the major control is energized through a circuit extending from switch S11a, wire 163, contacts 132b, switch S13b, relay magnet 165, contacts P8, to line 91. Closure of contacts 165a will provide a holding circuit and

will also provide a branch circuit to major socket C-3 which is completed through the appropriate zero button magnet 157.

It will be apparent that when only a minor group change occurs contacts 103c and 132b are open so that the intermediate and major accumulators are not reset. Also if there is but an intermediate group change, contacts 132b are open, thus permitting resetting of the minor and intermediate accumulators only.

Thus far it has been shown how the automatic starting, automatic resetting, and machine operating circuits are controlled and how the automatic control mechanism functions to keep the machine running. For certain classes of work it is desired to have the machine, upon a change in group classification data, enter upon one or more so-called total transfer cycles of operation and to suspend total taking and resetting operations until these transfer cycles have been completed. The manner in which these transfer operations are initiated and carried out will now be explained.

Transfer cycle controlling circuits

Referring now to Fig. 11, the switch S3a (L4) is moved to its dotted line position when total transferring operations are to be performed. In this position the card feed clutch magnet 22 is connected in series with pairs of relay contacts 136a, 300b, and cam contacts L4. In parallel with contacts L4 are switches S17a, S19a and minor control relay contacts 97e. The contacts 136a are closed when magnet 136 is energized as explained in Patent No. 2,131,226 under the heading "Third transfer cycle" or 300b are closed during a total transferring cycle in a manner to be explained under the heading "Entering '100' in section I of accumulator 6" and during a following reset cycle, as will be pointed out, the contacts 97e are also closed. This sets up a circuit for relay magnet 137 which follows from line 80, relay magnet 137, switch S21b, contacts 136a or 300b, switches S17a, S19a; contacts 97e to line 91. Relay 137 closes its contacts 137a which provide a holding circuit for the relay and at the same time short circuit contacts 136a or 300b so that they may thereafter open. In this manner, a circuit is provided for the card feed clutch magnet 22 which is maintained until the group control mechanism causes opening of contacts 97e. This will break the card feed clutch circuit and the machine will perform total transfer cycles without accompanying card feeding.

Switch S3b (R3) is also moved to its closed position to provide a holding circuit for the main drive clutch magnet 99 after card feeding operations have been interrupted. This circuit is traceable upon closing of contacts 97a (R4) upon a group change as follows: from right side of line 91, contacts 97a, switches S17b, S19b, S21a, contacts 136b or 300a (according to the setting of switch S21a), switch S3a (now closed), switch S9d, contacts 95a (C3), relays 95, 100, and 104, clutch magnet 99, contacts P1, to line 90.

At the completion of the total transferring operations, contacts 136b or 300a, as the case may be, open to interrupt the circuit.

Switch S3c (R5) is open for total transferring operations so that automatic reset operations do not take place when the minor control relay contacts 97a close. The machine will now perform a succession of cycles of operation without accompanying card feeding or printing and as the machine is arranged, these extra cycles may be one,

two, or three in number, for certain types of problems, and may be of a more indefinite number for other types of problems.

The manner in which the machine enters upon one, two or three extra cycles is dealt with in detail in my copending application (Patent No. 2,131,226) under the heading "Transfer cycle controlling circuits" and involves circuits located at C17 to C20 which under control of switches S10b, S15 and S16 permit energization of relay magnet 136 (C21) after one, two, or three transfer cycles.

For the operation of the machine enabling the solution of banking problems the contacts controlled by relay 136 are ineffective. The relay magnet 300 (L45) instead performs similar functions and causes the machine to perform a number of transfer cycles equal to the difference in value between date representing numbers on two record cards as will be explained. Circuits controlled by relay 136 will, however, be traced hereinafter to enable a better understanding of the prior art operation as set out in my Patent No. 2,131,226.

Relay magnet 300 functions to terminate the transfer cycles of operation and initiate an automatic total taking and resetting cycle and at the same time causes recoupling of the card feeding mechanism to the main drive mechanism of the machine.

Energization of magnet 300 causes opening of a pair of contacts 300a which take over the function of the contacts 136b and (R3) which are in the main clutch magnet circuit traced above (when switch S21a is in full line position), so that the circuits to the tabulating motor TM will be interrupted. The contacts 300c (R6) will close to take over the function of the contacts 136c and permit initiation of the automatic total taking and resetting cycle (when switch S22b is open and switch S22a is closed).

A third set of contacts 300b (L4) will close to take over the function of the contacts 136a and complete the circuit through card feed clutch magnet 22 and relay magnet 137, which latter provides a holding circuit for the clutch magnet so that upon automatic resumption of the card feeding and accumulating operations which follow the total taking cycle, the card feed mechanism will be already in operating condition.

The description thus far has pointed out how the motor operating circuits of the machine are controlled through the several types of cycles under control of either magnet 136 or magnet 300. The control by magnet 136, when it is conditioned to control, is in the usual manner as set forth in Patent No. 2,131,226. The control by magnet 300 which is effective when the machine is conditioned for the solution of banking problems will cause the operation of the same functions as magnet 136, the difference lying in the time of operation which is dependent upon the time of energization of magnet 300. The manner in which the data are read from the record cards and entered into the accumulating and printing devices and the manner in which transferring of data from one accumulator to another is effected during transfer cycles will now be explained.

Adding and printing circuits

The adding magnets 25 (C34, C35, C36) are wired to plug sockets 143 from which plug connection may be made to the lower brush sockets 120 (see Fig. 10). The adding circuit may be traced therethrough as follows: from line 90, (Fig. 11d) to contacts 25a (C33), adding magnet 25, plug socket 143 (Fig. 10), connection to socket 120 (R32),

lower brush LB, impulse distributors 122 (R25), wire 123, lower card lever contacts LCLd, contacts 103a, contacts 97b, to line 91.

The print magnets 55 (L33) are wired to plug sockets 147 through relay contacts 145a which are adapted to be closed during listing operations. A plug connection is made between sockets 147 and lower brush sockets 120 in positions in which printing is to be effected. The printing circuit may then be traced from lower brushes (R32), 10 socket 120 (Fig. 10), connection to socket 147 (C33), contacts 145a, print magnet 55, to line 90. In this manner the adding magnet 25 and the corresponding printing magnet 55 are concurrently energized through the circuits traced and the number represented by the location of the perforation will be entered into the adding mechanism and printed under control of the printing mechanism.

Total printing circuits.—During total taking 20 operations the printing magnets 55 are connected to plug sockets 148 (C33) through relay contacts 149a which are closed during total taking operations in a manner to be set forth. The sockets 148 may be connected to sockets 150 (R33) of the accumulator read-out mechanism. The location of these sockets is shown on the plugboard (Fig. 10) where representative plug connections 151 are shown for accumulator 4 and accumulator 5. During the total taking cycle, circuits will be completed through the read-out devices of the accumulator at differential times according to the position of the contact wipers 32 (R33) through circuits of which the following is representative: from line 91 (Fig. 11c) through wire 152 (R25), cam contacts SP12, wire 153, a series of cam contacts SP1—SP9, which close in succession to emit impulses to wires 154.

These wires extend through cable 155 and terminate in contacts 156a (R34). Contacts 156a are normally closed and connect the bars 35 of the read-out device to the appropriate emitting contacts SP1 to SP9.

Assuming now that a wiper 32 is positioned to represent "8", the total printing circuit will follow through the SP8 contact timed to close at the "8" time in the cycle and thence through the "8" wire 154 to the "8" contact 156a to bar 35 and thence through wiper 32 to bar 34, plug socket 150 (Fig. 10), connection 151, to socket 148 (C33), contacts 149a, print magnet 55, to line 90.

List selection.—It will be recalled that in tracing the listing circuits it was pointed out that relay contacts 145a (C33) would first have to be closed before such circuits could be completed. The manner in which the controlling relay 145 is energized to cause such closure of the contacts will now be explained. These relays are shown at L30 and terminate in plug sockets B—1 to B—7, one for each printing bank. From sockets B—1 to B—7 a plug connection may be made to a plug socket A—1 (C28) through a connection 168 (Fig. 10). With this connection, a circuit is completed every cycle of the machine, which circuit extends from line 90, cam contacts L18 (L25), lower list contacts 169, which are manually positioned as shown for listing operations, plug socket A—1, plug connection 168, socket B—1, relay magnet 145, relay contacts 140b (L28) whose controlling coil 140 is energized during transfer cycles, wire 170 (Figs. 11b, 11a, and 11), contacts 104a (C2) to line 91. In this manner the contacts 145a in the listing circuits are closed during each entering or adding cycle of the machine. The circuits through which relay coil 140 is energized 75

are traced hereinafter under the heading "Initial transfer cycle."

A plug connection to socket A—2 (C25) will cause printing of designating data from the first card of each minor group only. A connection to socket A—3 (C26) will cause printing from the first card of each intermediate group and a connection to socket A—4 (C27) will cause printing from the first card of each major group only. The detailed explanation of these controls is given in my copending application (Patent No. 2,131,226) under the headings "Group indicating on minor change," "Group indicating on intermediate change," and "Group indicating on major change" and since their functions are not of prime importance here, such explanation will not be given.

Total print selecting circuits

The manner in which the relay contacts 149a are closed to control the total printing circuits will now be described.

Each group of contacts associated with a printing bank is controlled by a relay magnet 149 (R22) 25 each of which is connected to a plug socket D—1 to D—7 through relay contacts 179a. From sockets D—1 to D—7 a plug connection 180 (see Fig. 10) may be made to one of the three sockets C—1, C—2 or C—3 which, as explained, are associated with the group control mechanism so that a plug connection made from socket D—3 to the uppermost socket C—1 (L8) will cause energization of the associated relay magnet 149 for total printing during minor, intermediate and major total taking cycles and connection to the other two sockets C—2 and C—3 would cause total printing on intermediate and major total and major taking cycles alone, respectively. These circuits are controlled by cam contacts SP12 (C25) which upon closure complete a circuit from line 90, relay magnet 179 (L25), contacts SP12, to line 91. Magnet 179 will close its related contacts 179a (R22) so that the selecting circuits may be completed from line 91, wire 152 (R25), contacts SP12, switch S8 (closed for total printing operation), relay magnet 149, contacts 179a, socket D—3, plug connection 180, to socket C—3 and from thence to left side of line 90 through circuit paths already described.

In this manner selected printing banks are connected to their associated accumulators during selected total taking cycles.

At L9 are shown a pair of sockets C—4 and C—5 to which plug connection may also be made to the sockets D—1 to D—7. Connection made to the socket C—5 will cause energization of the associated print selecting magnet 149 during each total taking cycle regardless of its character and connection made to the socket C—4 will effect similar operation under control of relay contacts 111b which are in series with this socket. The controlling magnet 111 for contacts 111b are shown at L5 and the circuits for controlling this magnet are explained in detail in my Patent No. 2,131,226 under the heading "Progressive totaling."

Progressive totaling

The machine may be conditioned for so-called progressive or sub-totaling, that is, total printing without accompanying resetting of the accumulators.

Such type of operation is fully explained in my copending application (Patent No. 2,131,226) under the heading "Progressive totaling" and since an understanding thereof is not essential to

the present improvements, its explanation will accordingly not be given herein.

Transfer operation after minor group change

If it is desired to have transfer cycles take place upon a minor group change with an intervening progressive total printing cycle, the switches S3a, S3b, S3c, and S4 are shifted from the positions in which they are shown on the circuit diagram so that upon the occurrence of a minor group change and the consequent interruption of tabulating operations, the progressive total printing cycle will be initiated through switch S3c (R5).

A single transfer cycle is now to follow which involves the re-establishment of the main drive clutch circuit through a circuit traceable from line 91 (R4), contacts 97a, switches S17b, S19b, S21a, contacts 300a, switch S3b, now closed, contacts 111g (closed during progressive total cycle), contacts UCLb, contacts 102, contacts LCLc, cam contacts P2, which close momentarily during the progressive total printing cycle, switch S1, now closed, contacts 101, magnets 95, 100, 104, and 99, contacts P1, to line 90. A tabulating cycle of operations will now follow without accompanying card feeding since switch S3a (L4) is in its dotted line position and contacts 136a and 300b are open. During the cycle the circuit through closed switch S4 (R17) will be completed and since switches S15 (C19) and S16 are closed, the relay magnet 136 (C21) will be energized in the manner more fully explained in my copending application, (now Patent No. 2,131,226) under the heading "Third transfer cycle" to operate its associated contacts of which contacts 136a (L4) will re-establish the card feed clutch circuit. Contacts 136c (R4) will

more transfer operations are to take place, the resetting cycle will be delayed as explained herein after, under the heading "Problem" for additional cycles at the completion of which the relay magnet 300 will be energized and resetting will take place after the transfer cycles have been completed.

Thus upon a group change the machine will execute a progressive total printing cycle to print the amounts standing on the accumulators and will then automatically enter upon a transfer cycle or cycles of operation followed by another total printing cycle during which the accumulators may be reset.

15 If desired, the progressive total printing cycle may be eliminated and transfer cycles effected immediately upon the occurrence of the group change. For this type of operation the progressive total switches S9a, S9b, S9c, S9d, S10a, S10b, S10c, S11a, and S12 are set in positions on the wiring diagram.

Settable switches

25 Thus far the various types of machine cycles which may take place in varying sequence have been set forth. These have been:

Card feeding and accumulating cycles

Resetting cycles

Transfer cycles

30 Total printing cycles

In the conditioning of the machine to effect selected cycles in any desired order, various switches have been pre-set and in order to summarize the operation of the switches they are listed below in tabular form, giving their location on the circuit diagram and identifying the functions which they perform.

	Switch	Location	Function when shifted
Transfer	S1	C4	Permits completion of the automatic restarting circuit.
	S2	R6	Permits completion of the automatic resetting circuit.
	S3a	L4	Shifts control of the card feed clutch magnet for transfer operations.
	S3b	R3	Permits separate control of the main clutch circuit for transfer operations.
	S3c	R5	Shifts control of the reset magnet circuit for transfer operations.
	S4	R17	Permits completion of the transfer cycle controlling circuits.
	S5	R25	Permits completion of the total printing control circuits.
	S6	C10	Renders major control operative.
	S7	C11	Renders intermediate control operative.
	S8	C12	Renders minor control operative.
Progressive total printing	S9a	L5	Permits completion of the circuit through relay 111.
	S9b	L6	Permits repeated reset circuit completion.
	S9c	R5	Closes automatic reset circuit.
	S9d	R3	Shorts contacts 111g.
	S10a	R3	Permits completion of restarting circuit.
	S10b	C18	Permits completion of transfer cycle controlling circuits.
	S10c	C5	Permits completion of print clutch circuit.
	S11a	L12	Permits completion of zero button circuit.
	S12	L12	Permits completion of automatic shunt circuit.
	S13a	L6	Permits completion of reset shunt circuit for repeated reset operation.
Successive resetting	S13b	L10	Prevents completion of major zero button circuits.
	S14a	L10	Prevents completion of intermediate zero button circuits.
	S14b	L12	Causes successive reset cycles.
	S15	C19	Eliminates first transfer cycle.
Repeated transfer	S16	C20	Eliminates second transfer cycle.
	S17a	L4	Permits completion of card feed clutch circuit on major group changes.
	S17b	R1	Permits completion of automatic starting circuit upon major group changes.
	S18a	R5	Permits completion of automatic reset circuit on major group changes.
Transfer after major group change	S18b	R18	Permits completion of transfer cycle circuits upon major group changes.
	S19a	L5	Permits completion of card feed clutch circuit on intermediate group changes.
	S19b	R2	Permits completion of automatic starting circuit upon intermediate group changes.
	S20a	R5	Permits completion of automatic reset circuit on intermediate group changes.
	S20b	R18	Permits completion of transfer cycle circuits upon intermediate group changes.

re-establish the reset circuits during which total printing and resetting will take place. If two or

The above switches and their functions are all 75 fully explained in my copending application (now

Patent No. 2,131,226). For the purposes of the present invention several additional switches are provided which are similarly identified in the following table:

Switch	Location	Function when shifted
S21a	R3	Removes main drive circuit from control of contacts 300a.
b	L4	Removes printing clutch circuit from control of contacts 300b.
S22a	R5	Places reset circuit under control of contacts 300c.
b	L48	Permits completion of total printing circuit on intermediate group change.
c		Removes relay 191-V from control of contacts 300d.
d	R19	Removes relay 191-V from control of contacts 300d.
S23a	L24	Connects relay 320 for transfer operations.
b	C46	Completes return circuit to relay 300.
c	C23	Opens circuit to contacts 140k.
S24	L47	Completes holding circuit to relays 318 and 333.
S25	L41	Changes common circuit connection to sec. II of ACC#6.
S26a	C18	Shift transfer control circuits.
b	L22	Render double step relays effective.
S27a	L24	Render inverting relays 156 ineffective.
S27b	L22	
S29b	L22	

The switches listed above are grouped and identified with legends which indicate the machine operations for which they are shifted from the positions shown in the circuit diagram. Thus switches S3a, S3b, S3c, and S4 are shifted whenever transfer operations are to be performed and switches S15 and S16 are open when there are to be two or three transfer cycles, respectively.

The groups of switches embraced in brackets in the above tables may be mechanically connected for concurrent shifting or they may be shifted individually according to the requirements of the problem.

If the transfer cycles are to take place after a major group change, the switches S11a, S11b, S18a and S18b are shifted, and if transferring is to be effected after an intermediate group change, the next four switches are shifted. It will be apparent that various combinations of conditions may be set up by shifting the groups of switches in various combinations and the machine thus lends itself to the solution of a great variety of problems, certain of which will be set forth hereinafter.

Transfer operations

For transferring of an amount from one accumulator to another, plug connections are made from the read-out plug sockets 150 (R33) of one accumulator to adding plug sockets 143 of the accumulator to which the data is to be transferred and the transferring circuit will be completed through the read-out device of the first accumulator in the same manner as explained in connection with reading out the total to the printing mechanism. Since during transferring, however, the impulse emitting contacts SP1 to SP9 are inoperative, use is made of a second set of impulse emitting contacts ZL1 to ZL8 (R26) which close successively during each machine operation to emit impulses to the wires 154.

Intermediate the contacts and the wires are relay contacts 140a controlled by the relay magnet 140 (C17) which is energized throughout the transfer cycles of operation as explained under "Initial transfer cycle" so that during a transfer cycle the amount standing on any accumulator will be transferred directly to any other accumulator under control of contacts ZL1 to ZL8.

For certain classes of work, the entering circuits of the accumulators are connected to the lower brushes through distributing relay contacts

191a (R20) which are normally closed as shown during entering operations.

The normally open contacts 191b terminate in plug sockets 192 and 193. The third blade of the relay contacts is connected to a plug socket 194.

The sockets in Fig. 10 are labelled "center," "closed," and "open" for facility in identifying them as wired to the center blades, outer, normally closed blade, and outer, normally open blade.

Reference to plugboard diagram (Fig. 10) will show the location of the several plug sockets, and after inspection of Fig. 14 it will be readily apparent how plugging connections are effected.

The contacts 191a and 191b are provided in groups of nine, each controlled by distributing relay magnet 191. The machine is provided with six such relays whose plugboard sections are labelled I to VI in Fig. 10. As will be hereinafter explained, the magnets 191 may be selectively operated during the several cycles to shift the related contacts so that if during the entering cycle the magnet 191—I is energized closing the contacts 191b associated therewith, it will be noted that

the lower brushes LB are connected through the contacts 191b to accumulator #2. During the first transfer cycle, the magnet 191—II will close its contacts 191b and accumulator #3 will be connected to accumulator #2 for transfer between the two, and on another transfer cycle, the magnet 191—V will connect the read-out device of accumulator #3 to accumulator #4. In Fig. 14 but a single set of contacts 191a, 191b has been shown for each coil 191 but it will be understood that there is a similar set of contacts used for each denominational order involved.

Subtractive transferring.—It may be desired instead of directly transferring the number standing on an accumulator to another to transfer the complement whereby the resulting number will represent the balance of those merged. This is brought about as follows: a relay 156 (L22, L24) is provided for each accumulator and the associated contacts 156a and 156b are shown at R34, R35, and R37. The contacts 156b are connected through wires 202 and cable 155 (R38) to the emitting contacts SP1 to SP9 in a complementary relationship; that is, the SP1 contact is wired to the "8" contacts 156b; the contacts SP2 are wired to the "7" contacts 156b, and so on. Thus, if any relay 156 is energized, the associated read-out devices will be disconnected from wires 154 and connected to wires 202 so that the number transmitted will be the nines complement of the number standing on the accumulator.

The relay magnets 156 are arranged so that they may be selectively energized during any of the transfer cycles and are accordingly wired to plug sockets 0—1 to 0—6 from which connection may be made to socket N—1 (C—18), N—4 (C—19), N—2 or N—3 (C19, C20).

The plug socket N—4 (C19) may also be connected to sockets K—1 to K—6. When so connected, the selected magnets 191 or 156 will be energized for each transfer cycle and transferring either straight or complementarily will occur each transfer cycle from the selected accumulator. The circuit to magnet 156, for example, is traceable from right side of line, switch S4 (R17), contacts SP10, switches S18b, S20b, contacts 37g, contacts 138a, socket N—4, connection to socket 0—2 (L22) switch S21b, magnet 156, to line 90.

Balance selection

In the transference of items from one accumu-

lator to another additively and subtractively, it is apparent that the status of the balance may change between negative and positive and such status is determined by means of a so-called double-step relay which is brought into operation through plug connections to be described.

When balances are obtained by complementary addition in which items of one class are entered in their actual value and those of another class in their complementary value, it is clear that a change in the type of balance; that is, a change from a credit or positive to a debit or negative balance or vice versa, can only occur when an item of the class to which the balance changes is added. If the credit items are entered according to their positive value and the debit items according to their complementary value and a credit balance stands on the accumulator at the time, it can only be changed into a debit balance, if a debit entry is made. This will be clearer from a specific example. If a credit value designated by 160 stands on the accumulator and a debit item mounting to 270 is entered in its complementary value of 99730, the character of the balance would be changed thus:

Credit value.....	160
Complement of debit item 270.....	999999730

Resulting in a debit (complementary) of	999999890

In another case, if a credit balance stands on the accumulator and a debit item of smaller value is complementarily added, the character of the balance does not change, thus:

Credit value.....	160
Complement of debit item 29.....	999999971

Resulting in a credit balance of.....	000000131

It will be noted that at the end of the actual entry of the complement the accumulator elements to the left of the significant figures in this case stand at zero and that the nines were disposed of through a carrying operation which takes place in the latter part of the machine cycle after the actual entries.

This carrying operation in the extreme left hand accumulator wheel through which the nine entered from a debit item (complementary) is disposed of is made use of in conjunction with the special debit indicating perforation which is made in a selected column of each record card usually in the "X" index point position to designate such card as being a debit card.

In order to print as a true amount a value standing in an accumulator as a complement, it is obvious that the impulse emitting mechanism will have to emit impulses in transposed order to the accumulator read-out devices in order to print this true number. This transposition is effected by the double-step relay shown in Figs. 8 and 9.

It is apparent that two impulses to the magnet 79 are required to change the condition of the contacts and restore them again to normal. Thus, the first impulse may be derived from an "X" punched card denoting a negative item. This will set the contacts in condition to effect the true printing of negative balance as will be shown, providing a second impulse is not received by the relay to return the contacts to normal condition to print a positive balance. Whenever the negative balance in the accumulator becomes posi-

tive, the highest order wheel passes from nine to zero and closes the contacts 160 of Fig. 6 at the same time that it adds the elusive one to the lowest order. Closure of contacts 160 provides the second impulse to the magnet 79 to restore it to normal condition to print a positive balance.

When balancing, a rule may be stated with regard to the action of the double-step relay; namely, if the number of primary impulses as from "X" punched cards plus the number of secondary impulses as from the highest order carry mechanism results in an even number, the relay contacts will be in even or normal condition; consequently, there will be no transposition of the emitter lines to the reading-out mechanism. In consequence, normal impulses will be received to print or transfer the balance.

Conversely, if the number of primary impulses plus the number of secondary impulses results in an odd number, the relay contacts will be in odd or abnormal condition and will transpose the emitter lines to the accumulator read-out mechanism, thus providing complementary impulses to control the type bars to print complementary to nine in all denominations.

Primary impulse to double-step relay.—Referring to Fig. 11a the upper brush plug socket 117 (R10) which is connected to the upper brush which traverses the column of the record card in which the special item indicating perforation is made is connected by a suitable plug wire as 200 (Fig. 10) to a socket 207 (L17). A cam contact T5 is adapted to close momentarily as this index point position is passing the upper brushes UB so that when a special "X" perforation is analyzed, a circuit may be completed from left side of line, wire 116 (L13), upper brush UB, socket 117, plug connection 200, to socket 207 (L17), cam contacts T5, relay magnets 208, 209, to line 91. This circuit is held by contacts 208a which hold the circuit through wire 210 and contacts T2 (L13).

During the following adding cycle a circuit is completed from line 91, contacts 97b (R3), contacts 103a, lower card lever contacts LCLd, wire 123, wire 211 (R21), contacts 140g, cam contacts L17, relay magnet 212, to line 90. A parallel circuit extends from contact L17 through wire 213, contacts 208b, closed due to the presence of a special indicating perforation, to socket P—1 from which the circuit extends through plug connection 215 to a socket R—1 (see Fig. 10), thence through contacts 212a (closed by relay 212), double-step relay magnet 79, switch S27a, to line 90. In this manner, the double-step relay magnet receives the so-called primary impulse whenever a credit designating perforation is sensed by the upper brushes and which indicates that a complementary value is about to be entered into the accumulator. The particular magnet 79 which is energized is the one which has been associated with a particular accumulator and the magnet 79 now under discussion is the upper magnet 79 in Fig. 11b. It should be borne in mind that there are six such magnets provided, one for each accumulator, but only two thereof are shown. The present explanation refers to the upper magnet 79 and the usual control of such magnet is as set forth in the Patent No. 2,131,226 under the similarly identified headings.

When transfer operations are being performed, the primary impulse may also be impressed upon the double-step relay magnet 79 when an amount is transferred subtractively from one accumulator to another. The circuits involved in providing the primary impulse to the transfer cycles will

now be traced in connection with the lower magnet 79 in Fig. 11b.

During transfer cycles the relay 140 (C17) is energized. The manner of energization is explained in my Patent No. 2,131,226, and is briefly as follows:

With switch S4 (R11) closed, a circuit will be completed upon deenergization of the minor control relay 97 which is traceable from line 91, switch S4, contacts SP10, switches S18b, S20b, relay contacts 97g, now closed, switch S10b, cam contacts L15, switch S26a, relay magnet 138, wire 139, to line 90. Magnet 138 closes its contacts 138a to provide a holding circuit for the relay magnet. A parallel circuit is also traceable from contacts L15 through a magnet 140. This magnet controls the circuits through which transferring is effected from one accumulator to another. This will cause closure of contacts 140f (C21) so that a circuit will be completed from line 91, contacts 140f, contacts L17, relay magnet 212, as during adding cycles. A parallel circuit will follow from contacts L17, wire 213, wire 217, contacts 141f, contacts 138f, plug socket Q-1, plug connection 219 (see Fig. 10), to socket R-5, contacts 212a, double-step relay 79, switch S30a, to line 90. The controlling magnet 141 for contacts 141f is energized as explained later under "Repeated transfer cycles," near the end of the first transfer cycle and held energized until the following total taking cycle. Thus a circuit is completed to lower magnet 79 only during the first transfer cycle. Other sockets Q-2 to Q-7 are provided, any one of which may be connected to the socket R-5 to cause magnet 79 to be energized in other transfer cycles. My Patent No. 2,131,226 explains under "Primary impulse to double-step relay" which of the Q sockets control the impulse to the relay. Briefly, a connection 219 to socket Q-1 will permit an impulse during the first transfer cycle only of a series of transfer cycles. Q-2 is effective during the second only. Q-3 is effective during the third and subsequent transfer cycles. Q-4, Q-5 and Q-6 are each effective during the second and subsequent transfer cycles and Q-7 is effective during all transfer cycles. In this manner the double-step relay may be energized during a selected transfer cycle. Contacts 138f are closed during the first transfer cycle due to the energization of their controlling relay 138 at such time as will be pointed out under the heading "Initial transfer cycle." Thus, any relay magnet such as the upper magnet 79 may be connected to receive an impulse during a card feeding cycle when a special "X" hole is sensed, or any magnet 79 may be connected as is the lower magnet 79, to receive an impulse during a transfer cycle as an incident to the energization of relay magnets 140 and 138 during a transfer cycle.

The upper magnet 79 will cause closure of a pair of contacts 79a (L22) and when contacts 100a close upon deenergization of magnet 100, a circuit is completed which extends from line 90, inverting relay 156, contacts 79a of the upper magnet 79, wire 220, contacts 100a, to line 91.

In the prior machine of Patent No. 2,131,226, the circuit for energizing magnet 156 is the same for each of the magnets 156 and is as traced for the upper magnet 156 associated with the upper magnet 79. In the prior art machine energization of magnets 156 cannot take place until contacts 100a close upon deenergization of their controlling magnet 100. This magnet 100 (C3) is in the main drive clutch circuit so that

the magnet is energized as long as card feeding and transferring operations are taking place and becomes deenergized following a group number change and the initiation of a total taking cycle. It follows, therefore, that in such earlier machine magnets 156 were effective to shift their related contacts only during total taking cycles. The control of the energizing circuit of at least one of the magnets 156 for the purposes of enabling energization of a magnet 156 during transfer cycles has been modified in the present machine. To this end contacts 140p and 140k (L23) are provided, which shift during transfer cycles so that contacts 79a of the lower magnet 79 are normally connected to contacts 100a during card feeding and total taking cycles through contacts 140p and are connected directly to line 91 through contacts 140k and a switch S23c during transfer cycles. Also for the purposes of the present invention contacts 93a, 93b, 318e and 318f are connected intermediate the lower magnet 156 and its related lower contacts 79a, as shown, and contacts 79c are further provided. The conditions under which the first named contacts are shifted under control of magnets 156 are set forth hereinafter under the heading "Intermediate group change." Magnet 93 is the reset clutch magnet shown at (C1) and is energized during total taking cycles.

Thus, the lower magnet 156 is energized during total taking cycles through a circuit from line 90, lower magnet 156, contacts 93b (closed during total taking), lower contacts 79a, 140p and 100a to line 91. During transfer cycles the circuit is from line 90, lower magnet 156, contacts 93a, 318e, lower contacts 79a, contacts 140k, switch S23c to line 91. The arrangement shown permits energization of lower magnet 156 during a transfer cycle when contacts 79a are open, provided contacts 318e and 318f are shifted. Under such condition the circuit is traceable from line 90, lower magnet 156, contacts 93a, 318f, 79c and 140k, switch S23c to line 91.

Secondary impulse.—If the highest order of the accumulator receiving the complementary amount passes from nine to zero, indicating that the addition of the negative amount resulted in a positive balance, the contact 160 (Fig. 6) of an accumulator will have closed momentarily. This provides a further or secondary impulse to the upper double step relay magnet 79, for example, through a circuit traceable from line 90, switch S27a (L22), upper relay magnet 79, contacts 160, contacts 221a, contacts L18, to line 91. Contacts 221a are closed by relay 221 (C21) which relay is energized through contacts L18. If the machine enters upon a total printing or transferring cycle of operations after the double-step relay has received an odd number of impulses, the related relay magnet 156 will have been energized through the closed contacts 79a and the associated accumulator will have its contacts 156b (R34) closed so that complementary impulses will be transmitted to cause printing or transferring of the true value of the complement amount standing in the accumulator.

It will be understood that there is provided a double step relay 79 and inverting relay 156 for each accumulator and that for each one plug connections may be made according to the operating requirements of the problem to be undertaken.

During the final total printing and reset cycle of operation the double-step relay 79, if it has received an odd number of impulses will receive

an additional impulse to restore it to normal position. This is effected as follows:

If the associated accumulator is to be reset on the total taking operation, a pair of contacts 157a (C23) which are closed by a zero button magnet 157 will complete a circuit from right side of line through cam contacts SP13 (C22) a pair of contacts 156c controlled by the reversing relay, contacts 157a, contacts 79b (closed if the relay is in "odd" position), magnet 79, switch S27a to line 90. Thus, on resetting, the "odd" condition of the double-step relay is restored to "even" or normal condition in readiness for the next group of cards.

Problem

The complete operation of the machine will now be explained with particular reference to the problem of Fig. 12 and the coordination of the various mechanisms and electrical devices will be set forth. The connections involved are diagrammatically shown in Fig. 14. It is assumed that the record cards relating to a particular account number comprise three transaction cards indicating transactions on the first, third, and twentieth days of the accounting period, a closing card having a day number 30 and an additional discount controlling card representing a further transaction and having a day number of 3. The machine is first sent through the usual preliminary reset cycle initiated by the manual closure of reset key contacts 92 (C5) which establishes the circuit to the reset motor RM as explained under the heading "Initial resetting circuit." As also explained, the automatic control circuits are set up to energize and hold the control relay magnets 97, 103 and 132 through the circuits traced under the headings "Minor holding circuit," "Intermediate holding circuit," and "Major holding circuit." Upon completion of this resetting cycle, the machine stops.

With the accumulators thus cleared and the group control set up, the operator presses the start key to close contacts 98 (C3) resulting in energization of the motor TM, the main drive clutch magnet 99 (L3) and the card feed clutch magnet 22 (L4) through the circuits traced hereinabove. There now follows two card feed cycles followed by an automatic reset cycle and then card feeding resumes automatically. These preliminary cycles may be termed the first and second preliminary feed cycles and the second preliminary reset cycle. For a better understanding of the relationship between these customary cycles and the sequence of events involved in the solution of the particular problem at hand, these cycles will be reviewed at this point.

First preliminary feed cycle.—During this cycle the first card is advanced by the picker from the hopper to the upper brushes, i. e., at the end of the cycle the leading margin of the card is under the brushes UB. Just before the end of the cycle the upper card lever contacts 109 close which, as indicated in Fig. 16, is after contacts L2 (R2) open and also after the group control test contacts L8, L9, and L10 have opened and closed again. Therefore, during this cycle contacts UCLd and LCLe are in the positions shown in Fig. 11a when contacts L8, L9 and L10 open and the shunt holding circuit is maintained through these contacts traceable from line 90, contacts 97d (L12), magnet 97, contacts LCLe and UCLd to line 91.

The intermediate control magnet 103 is held

through a circuit from line 90, contacts 103b (L11), magnet 103, contacts LCLf, LCLg, UCLg to line 91 while the major control magnet 132 is held through a circuit from line 90, contacts 132a (L10), magnet 132, contacts UCLf, LCLg, and UCLg to line 91.

No entries are made into the accumulators during this cycle as contacts LCLd (R4) prevent current to the brushes LB and contacts LCLk (C4) prevent the unit entries into accumulator #6. Also, since magnet UCL is not energized until after the entering part of the cycle, contacts UCLp (L42) and UCLk (L43) are open to prevent entries into accumulator #6.

15 *Second preliminary feed cycle.*—This cycle is initiated by continued depression of the start key or alternatively by pressing it a second time, as the machine would come to a stop after the previous cycle due to opening of the contacts L2 (R2) before the upper card lever contacts closed. Once the latter have closed, the contacts UCLb (C3) maintain the feed circuit until a group control change occurs.

The first card now passes brushes UB and its right hand day number (see Fig. 14) is sensed but no circuits will be completed for the following reason. The brushes UB which sense this field of the card are plug connected to the section II of accumulator #6, whose return circuit goes through switch S25 (L41), wires 319, and 124 to distributor 122, wire 123 to contacts LCLd (R4), which latter are still open at this time. This circuit is traced in detail later under the heading "Entering the day number." Consequently, no entries are made in the accumulators during this cycle, and the card advances to the lower brushes where at the end of the cycle its leading margin is under brushes LB. Meanwhile, the second card is advanced to the same position with respect to the brushes UB.

During the cycle, however, a group change is called to deenergize relay magnets 97, 103 and 132 to initiate a reset cycle. This is brought about as follows. With relay magnet UCL energized, contacts UCLd (C10), UCLg (C10) and UCLf (C11) are open with only contacts L8, L9 and L10 maintaining the holding circuits to the control magnets 97, 103 and 132. Therefore, when these contacts open after the sensing part of the cycle, the magnets become deenergized and contacts 97b (R3) open to interrupt the feed circuits.

55 *Second preliminary reset cycle.*—There ensues then an automatic reset cycle as explained under the heading "Automatic resetting circuits," during which the group control magnets are again set up and with switch S1 (C4) closed card feeding automatically resumes as explained under the heading "Automatic restarting circuit." The machine is now in what might be termed its "primed" condition in readiness to feed the first card past the brushes LB and the second card concurrently past the brushes UB.

60 It may be stated at this time that, as more particularly explained later under the heading "Initial transfer cycle," a transfer cycle precedes the reset cycle when two unlike cards have concurrently passed the upper and lower brushes. For the present reset cycle, however, there is no preceding transfer cycle for the reason now to be given. As explained under the heading mentioned, relay magnets 140 and 301 (C17) are energized upon a break in control, i. e. upon deenergization of magnet 97, so that contacts 301d (C42) close. At this time contacts L25 (C42)

are closed and as explained later under the heading "Comparing the day numbers in accumulator 6," magnet 300 (L46) is energized through a succession of circuits when sections I and II of accumulator #6 are of the same setting. The condition therefor exists during the latter part of the "Second preliminary feed cycle" wherein sections I and II both stand at zero, and magnet 300 is accordingly energized and opens its contacts 300a (R3) so that a possible circuit to maintain the main drive clutch 99 energized is broken. This circuit has been traced under the heading "Transfer cycle controlling circuits."

Contacts 300c (R6) are also closed at this time so that the second preliminary reset cycle is initiated by a circuit traceable from line 90, contacts L5, P3, magnets 93, 94, contacts 95d, switch S2 (now closed), contacts 26, 300c, switch S22a (now open), switches 318a, S20a, contacts 91a to line. The lower brushes LB which read the amount fields are wired through plug connections 601 to plug sockets 193 of the distributing relays 191-I (see also Fig. 10). Sockets 194 of the relay contacts are connected through connections 302 to the entering magnet sockets 143 of ACC#1 and through connections 303, to closed contacts 191a of further distributing relay 191-II to the entering magnets of ACC#3.

First card entry cycle

The contacts 191a are normally closed so that the amount sensed by the lower brushes will be entered in both accumulators #1 and #3. Where the amount represents a credit transaction, the record card contains a perforation in a selected column such as the perforation labelled X7, representing a hole in the X position of column 7. The column in which this perforation occurs is analyzed as the card passes the upper brushes and its presence causes the energization of the relay magnet 191-I, opening its contacts 191a and closing its contacts 191b so that as the card having the X7 perforation subsequently passes the lower brushes, the entry will be made through connection 304 to the adding magnets of ACC#2 only.

Credit perforation

The manner in which the X7 perforation causes energization of relay 191-I will now be explained with particular reference to the circuit diagram. The pickup circuit for this perforation is similar to that explained generally hereinabove under the heading "Primary impulse to double-step relay." The upper brush which traverses this credit card indicating column is connected to a plug socket 207-I (L14). As an X7 perforation passes the upper brushes, a circuit will be completed from upper brush UB (R10), plug socket 117, plug connection 230 (Fig. 10) to socket 207-I (L14), cam contacts T-3, timed to close at X, to a plug socket H-I from which plug connection 234 (Fig. 10) is made to the socket K-I (R18), thence through the related distributing relay 191-I, socket L-I, thence through a plug connection 235 to socket M-I and to line 91. In this manner, whenever a credit card is sensed, the circuit just traced will be completed and the distributing relay 191-I will be energized. The circuit will also flow from socket H-I (L14) through relay magnets 237, 238, to line 91.

Relay 237 will close its contacts 237a to provide a holding circuit for the distributing relay

which extends from line 90, contacts T2, (L13) contacts 237a, socket H-I and thence through the distributing relay 191-I as already traced.

Entering the day number

As the amount is being analyzed and entered into the appropriate accumulators, the day number field of the card is being analyzed by the lower brushes and at the same time the day number field in the next following card is being analyzed at the upper brushes. The circuits through which the numbers sensed are entered into the separate sections of ACC#6 will now be explained. The lower brush sockets 120 of the brushes which traverse the day field are connected to sockets 314 (see also Fig. 10) and as the card passes the lower brushes, circuits will be completed from the lower brushes through the connections to sockets 314 (C43) through normally closed relay contacts 315a, 301c, adding magnets 25 and contacts 25a of ACC#6, upper card lever relay contacts UCLk, to line 90. Plug connections are made from the upper brush sockets 117 to plug sockets 317 (C41, C42) and as the following record card passes the upper brushes, circuits will be completed through the upper brushes to sockets 117, connections to sockets 317, adding magnets 25 of section II, contacts 25a, upper card lever contacts UCLp, switch S25, relay contacts 318a, wire 319, wire 121 (Figs. 11d, 11c) to the impulse distributing contacts 122 (R25).

It may be pointed out that the cards have two day number fields, the one on the left being in accordance with a calendar day while that on the right (Fig. 14) may be an arbitrary number for accounting purposes, i. e. the left hand number may be the 12th day of some month while the right hand number may be the 46th day of a certain period.

Minor group change

The day number field at the left end of the card constitutes the minor group number field for group control purposes and is plug connected for minor control. The account number field is plug connected for intermediate group control and since the day numbers on succeeding cards are different, the group control mechanism will interrupt the card feeding circuits after each card. Thus, after the first card of the group has passed the lower brushes and the debit amount 50 entered into ACC#1 and ACC#3 and the day numbers 1 and 3 entered into sections I and II of ACC#6 as indicated in the first line of Fig. 12, the machine will automatically enter upon the balance transfer cycle of operations. This is brought about as follows:

The deenergization of the minor control relay 91 (L12) will cause opening of contacts 91e (C5) whereby the circuits controlling the card feed clutch magnet 22 are interrupted and card feeding operations will cease. The incidental closure of contacts 91a (R4) will cause the continued energization of the main drive clutch circuit through the normally closed relay contacts 300a (R3) included in the circuit through switch S21a. The main drive clutch circuit will remain energized until contacts 300a are opened and the card feeding operations will be suspended throughout such period.

Initial transfer cycle

There will now result the first transfer cycle during which the amount standing in ACC#2, which at this time happens to be zero, is trans-

ferred in complementary form to ACC#3. In order to effect this transfer, it is necessary to connect the emitting contacts ZL1, ZL2, etc. to the read-out section of ACC#2.

It is further necessary to operate the inverting relay contacts of ACC#2 and it is necessary to connect the read-out mechanism of ACC#2 to the read-in or adding section of ACC#3. This conditioning of the circuits is brought about as follows:

Closure of contacts 91g (C17) due to the minor group change will complete a circuit traceable from line 91, switch S4 (R17), cam contacts SP10, switches S18b, S20b, contacts 91g, switch S10b, cam contacts L15, relay magnet 140 to line 15 20. From contacts L15 a circuit extends through relay 301 (C17) which closes its contacts 301a to provide a holding circuit for the relay and maintain it energized during the interval that contacts L15 open. Magnet 140 closes its contacts 140a (R26) thus connecting the contacts ZL1, ZL2, etc. to the cable 155.

Concurrently with the energization of relay magnet 140, a circuit extends from cam contacts L15 (C18) through switch S26a, relay magnet 138, wire 139, to line 90, and this relay closes its contacts 138a to provide a holding circuit for the relay. A plug connection 204 (Fig. 10) is made between socket N-1 and the socket O-2 whereby a circuit is traceable during this first transfer cycle which follows from line 90, relay magnet 156 (L22), switch S27b, socket O-2, plug connection 204 (Fig. 10) to socket N-1 (C18) normally closed contacts 141d, contacts ZL13, relay contacts 138a, contacts 91g, switches S20b, S18b, contacts SP10 to line 91. Connection 204 associates the upper relay magnet (L22) with Acc. #2 with which accumulator the upper magnet 79 is also associated. It may be pointed out here that the lower magnets 156 (L23) and 79 (L24) are associated with Acc. #3. Energization of the upper magnet 156 will shift its contacts 156a, 156b, related to ACC#2 (R35) so that impulses will be transmitted to the commutator segments 35 in inverse order and the nines complement will be read therefrom. A further connection is made between sockets M-3 and L-2, and K-2 and J-4 (Fig. 10).

These connections have the effect of energizing relay magnet 191-II during the first transfer cycle. This circuit is traceable from line 90 (Fig. 11b) wire 139 (L18) socket J-4 (C18), plug connection to socket K-2 (Fig. 10), relay magnet 191-II, socket L-2, connection to socket M-3 (Fig. 10), contacts 141d to line 91 as traced before. The contacts controlled by relay magnet 191-II are represented in Fig. 14 and upon energization of the relay the related contacts 191a are opened and contacts 191b closed thereby completing the connection between the read-out commutators of ACC#2 and the entering mechanism of ACC#3. As mentioned before, since there is no significant entry in ACC#2, the amount transferred to ACC#3 will be a series of nines which, when added to the 50 standing therein, result in the number 49. However the carry mechanism of the units order which is mechanically controlled through the highest order, causes a "1" to be added, bringing the balance back to 50. During the last card feed cycle, minor control magnet 97 became deenergized to close contacts 91g (R17) and later in the same cycle contacts L15 closed so that magnets 140, 301 and 138 became energized near the end of this card feed cycle and, as will be explained, 75

magnet 141 becomes energized near the end of the next cycle which is the first transfer cycle. Therefore, during the initial transfer cycle contacts 138f and 141f (R22) are both closed and a circuit is completed as traced under "Primary impulse to double-step relay," through the connection 219 to energize the lower magnet 79, related to Acc. #3. When magnet 141 is energized near the end of the initial transfer cycle, contacts 141f open to prevent further impulses through connection 219. The result of this is to cause closure of the lower contacts 79a (Fig. 11b) setting the double step relay in its "odd" condition, as designated in the right hand column of Fig. 12 opposite the first "transfer" line. However, the entry of 9999 during the initial transfer cycle has caused the contacts 160 related to Acc. #3 to close and the secondary impulse is given to magnet 79 to restore it to its "even" condition. This circuit is traceable from line 91 (Fig. 11b), contacts L18, magnet 221 to line 90. Magnet 221 closes its contacts 221a establishing a further circuit from line 91, contacts L18, contacts 221a, 160, lower magnet 79, switch S30a to line 90. At the beginning of the second transfer cycle, therefore, the lower relay 79 associated with Acc. #3 is in its "even" condition as indicated in Fig. 12 and will remain so until a new series of transfer cycles is initiated following further card feeding.

Repeated transfer cycles

The machine is now ready to transfer the balance from ACC#3 to either ACC#4 or ACC#5. The determination as to which accumulator is to receive the entries is made by the double step-relay 79 associated with ACC#3. The double step relay 79 employed is the lower relay 79 in Fig. 11b and its condition during the several operations is indicated in the right hand column in Fig. 12 where DSR stands for "double step relay." The designation "even" means the contacts 79a of this relay are open and the designation "odd" means these contacts are closed. During the transfer cycles following the first, it is necessary to associate the read-out mechanism of ACC#3 with the entering mechanism of ACC#4 or ACC#5, and this is effected under control of relay magnet 191-V represented in Fig. 14. Energization of relay 191-V will connect ACC#3 to ACC#4 or ACC#5 through the contacts of a relay magnet 320. When this magnet remains deenergized, the entry will be made in ACC#4 and when energized, will be made in ACC#5. The manner in which relay 191-V is energized for all cycles after the first transfer cycle will first be explained.

A plug connection is made from the socket K-5 to a plug socket M-8 (C21) and Fig. 10 and a further connection is made from socket L-5 to socket M-2 (R18) and Fig. 10. Late in the first transfer cycle a circuit will be traceable from line 91, switch S4, contacts SP10, switches S18b, S20b, contacts 91g, 138a, contacts ZL10, magnet 141 to line 90. Magnet 141 closes its contacts 141b (C19) establishing a branch circuit from contacts 138a, switch S16 (which is closed), contacts 141b and magnet 142 to line 90. These relay magnets have contact points 141c and 142b respectively, in series with relay magnet 138 and a circuit is therefore completed near the end of the first transfer cycle which is traceable from line 90, wire 139, relay magnet 138 (C21), contacts 141c, 142b, socket M-8, connection to socket K-5, relay contacts 300d,

relay 191—V, socket L—5, connection to socket M—2, to line 91. This circuit remains energized throughout transferring operations at the termination of which contacts 300d open to de-energize the same. Continued energization of relay magnet 141 (C18) during the second transfer cycle will cause opening of a pair of contacts 141d in the circuits traced above which control the upper relay magnet 156 associated with ACC#2 and the relay magnet 191—II which controls connections between ACC#2 and ACC#3. These relays are accordingly deenergized after the first transfer cycle and their associated contacts restored to normal condition.

Energization of relay magnet 320 is controlled by the lower double step relay magnet 19 associated with ACC#3. This relay is provided with double contacts 19a, 19c (L24) which, when the accumulator contains a true number, is in its "even" condition as shown with contacts 19a open and when in "odd" condition; that is, with a complementary number standing therein, the contacts 19a are closed and contacts 19c open.

At such time, if switch S23a (L23) is closed, a circuit will be traceable from line 90, switch S23a, relay magnet 320, contacts 19a, 140k, now closed due to the energization of controlling magnet 140, switch S23c (C23) wire 321, to line 91. At the commencement of the second transfer cycle the double step relay of ACC#3 is in "even" condition as indicated in Fig. 12 so that the relay 320 remains deenergized and its contacts undisturbed. During this cycle therefore, the amount 50 will be transferred directly to ACC#4. Plug connections such as 322 (see Figs. 10 and 14) are made to sockets 193 of distributing relay 191—V. The contacts 191b of this relay are connected to the center contact blade of contacts 320a, 320b through normally closed contacts 323b controlled by a relay magnet 323. Contacts 320b terminate in plug sockets 324 which are connected through plug wires to the entering sockets 143 of the adding magnets of ACC#4.

Column shift connections

The relay contact arrangement through which entries are made to ACC#4 and ACC#5 are shown in the lower right hand portion of Fig. 11e and the normal connections are such that the units, tens, hundreds order and so on of ACC#3 are normally connected to corresponding orders of ACC#4 or ACC#5 as the case may be. This relationship may be changed under control of relay magnets 323 and 326. For example, if relay 323 is energized, its related contacts 323a (R44) will close, thereby connecting the sockets 193 (upon energization of relay magnet 191—V) with the sockets 324 of the next higher denominational order position. For example, the circuit from the units order socket 193 would follow through contacts 191b, contacts 323a, normally closed contacts 326b, contacts 320b of the tens position, to the tens socket 324 and thence, of course, to the tens order adding magnet of ACC#4.

If magnet 326 is also energized, the units order will be connected to the next higher order, namely, the hundreds, the circuit following from units socket 193, contacts 191b, 323a, 326a to the hundreds socket 324. This mechanism is generally referred to as column shifting mechanism and energization of relay magnet 323 has the effect of causing the transfer of ten times the amount standing in ACC#3 and energiza-

tion of both relay magnets 323 and 326, by shifting the denominational allocation two places, has the effect of causing the transfer of one hundred times the amount standing in ACC#3. The relay magnets 323 and 326 are shown at L44, L45 and are controlled in accordance with the setting of the commutator read-out devices of sections I and II of ACC#6. As long as there is disagreement in the setting of the units order commutator position of sections I and II, neither of these relay magnets will be energized. When the units orders are in agreement, magnet 323 will be energized. When the tens orders are in agreement the magnet 326 will be energized and when all three orders are in agreement, magnet 308 will be energized, which interrupts the transferring cycles of operation.

As shown in the upper right hand corner of Fig. 11e, the read-out commutator of the two sections of ACC#6 are wired as shown with the individual segments of each order wired to the corresponding segments 35a in the same order of the other section. The brushes in the several orders are shown in Fig. 11e in the positions they occupy when a "1" is entered in section I and "3" in section II according to the problem under consideration.

Comparing the day number in accumulator 6

As will be pointed out shortly, for each transfer cycle during which ACC#3 is read, the units order brush 33 of section I is advanced one step. After it has advanced two steps, a circuit will be traceable from line 90, cam contacts L25 (C42), relay contacts 301d, closed during transfer operations, conductor 34 of the units order section II, brush 33 in the 3 position, wire 328 to corresponding segment in the units order of section I, brush 33 now in the 3 position, wire 327, relay magnet 323, switch S23b (C46) to line 91. Magnet 323 closes contacts 323c setting up a holding circuit through cam contacts P1 which is maintained until the next following total taking cycle. Energization of magnet 323 will cause shifting of the related contacts 323a, 323b so that transferring thereafter will take place through the shifted circuits.

If the brushes 33 in the tens orders of sections I and II are also relatively displaced, the tens brush 33 in section I will thereafter be advanced one step for each transfer cycle until it occupies a position corresponding to the related brush in section II. At such time, a circuit is completed through contacts L25, 301d, the tens conductor 34 of section II, brush 33, segment 35a, wire 328, to the corresponding segment in the tens order of section I, brush 33 in that position, contacts 323d, now closed, wire 329, magnet 326, switch S23b, to line 91. Contacts 323c are closed to provide the holding circuit through contacts P1. Energization of magnet 326 will therefore cause further shifting of the connections between ACC#3 and ACC#4 as explained.

When the brushes 33 of the hundreds orders of sections I and II occupy the same relative position, a circuit will extend from the conductor 34 in the hundreds order position of section I through contacts 323e and 326e, now closed, wire 330 to relay magnet 308 and thence to line 91.

Entering units in section I of accumulator 6

The manner in which the brushes 33 of section I are advanced will now be explained. When relay magnet 191—V is energized, which, as ex-

plained, is during the first daily balance transferring cycle, a circuit will be completed from socket M-2, plug connection to socket L-5, continuing through a wire 331 (Fig. 11b at R20, Figs. 11c, d, and e) to cam contacts L24 (R41) thence through lower card lever contacts LCLk, normally closed relay contacts 300c, relay contacts 323f, normally closed contacts 318c, contacts 301b, now closed, units order magnet 25, to line 90. Cam contacts L24 are timed to close at "1" in the cycle so that a "1" will be added in the units order section I. Each succeeding transfer cycle will also cause "1" to be added in the units order until it is in agreement with the corresponding order of section II. At such time, as pointed out, the relay magnet 323 is energized, opening contacts 323f and closing contacts 323g. The circuit from contacts L24 will thereafter follow through contacts LCLk, 300e, 323g, now closed, 326f, 318c in the tens order of section II, 301b in the tens order of section I, tens order magnet 25 to line 90. The tens order of section I will be advanced unit by unit during successive cycles. When both tens orders are in agreement, magnet 326 will be energized and contacts 326g will be closed so that the circuit thereafter follows from contacts L24, LCLk, 300e, 323g, 326g, 318c in the hundreds order of section II, contacts 301b in the hundreds order of section I, magnet 25 in such order, to line 90, and the hundreds order magnet will thereafter be advanced unit by unit.

Total taking and reset cycle

For the example chosen in Fig. 12 where the difference between the two dates is two and the tens and hundreds positions in both sections stand at zero, it will be apparent that there is no stepping of these orders required and that as soon as the units orders are both standing at 3 the circuits previously traced individually will be concurrently completed so that magnets 323, 326 and 300 will be concurrently energized and transfer cycles will terminate at this point after the balance of 50 has been transferred twice to ACC#4. At this time, the machine will automatically enter upon a total taking and resetting cycle of operations, during which the amounts standing in ACC#1, 2, 3, 4, and 5 may be printed, if so desired, and ACC#6 will be zeroed. The total taking and reset cycle of operations is brought about under control of relay magnet 300, the opening of whose contacts 300a in the main motor circuit will interrupt the same. The closing of its points 300b (L4) will condition the card feed clutch magnet 22 for the resumption of card feeding after the reset cycle is completed. Closure of contacts 300c will, as explained above, automatically initiate the total taking and resetting cycle of operations by completing the circuit through reset magnet 93 and reset motor RM. During this cycle also, the opening of contacts SP10 (R17) will break the holding circuits for the magnets 140, 301, 138, 141, 142 and 136.

Second card cycle

At the conclusion of the total taking and resetting operation, the second record card containing a credit amount 25 and a date 3 is fed past the lower brushes while the next following card having a date entry of 20 is fed past the upper brushes. These two day numbers are currently entered into sections I and II of ACC#6 respectively, while the credit amount 25 is entered into ACC#2.

This credit card contains the X1 perforation explained in connection with Fig. 14 and causes energization of relay magnet 191-I so that the entry is made only in ACC#2. The minor group control mechanism again functions to detect the difference in dates between the second and third cards and as before, automatically initiates the first transfer cycle of operations during which the amount standing in ACC#2 is transferred to ACC#3 in complementary form, changing the double step relay associated therewith to "odd" condition. However, the mechanical carry operation which enters "1" into the units order changes the condition of the relay back to "even," leaving a debit balance amount of 25 in ACC#3. This operation of the lower double step relay 79 is effected in the same manner as explained for the first card, that is, when relay 138 (C17) is energized near the end of the card feed cycle, contacts 138f (R22) close to send the "primary" impulse to magnet 79 and, when contacts 160 (C24) close under control of the highest order of ACC#3, the "secondary" impulse is sent to restore the relay to its "even" condition. Further transfer operations now take place as before during which the amount 25 is successively transferred to ACC#4 seven times, at the termination of which the units orders will both stand at zero, thereby causing a shifting of the connections between ACC#3 and ACC#4 and also shifting of the unit entering circuits of section I so that on the following cycle, the amount 25 is transferred in ten times its value and the tens order section is advanced one unit, bringing section I to 20 which is in agreement with the 20 in section II. The relay magnet 300 is therefore again energized to interrupt transfer operations and total taking and resetting will again take place.

Third card cycle

The third card contains a credit entry of 70 and a date of 20, which latter is entered in section I while the date 30 is entered in section II from the last accounting period card of the group.

The first transfer cycle, during which the complement of 70 is transferred to ACC#3, changes the condition of the double step relay to "odd" and since the balance has now become a credit balance, there is no highest order carry and the double step relay remains in "odd" condition. This, as explained above, causes energization of relay magnet 320, which now closes its contacts 320a (Fig. 14) so that transfer is effected between ACC#3 and ACC#5. The amount transferred is, however, to be inverted before entry. This is effected under control of relay magnet 156 associated with ACC#3 (L23) which is energized concurrently with the magnet 320 through a circuit traceable from line 90, magnet 156, contacts 93a, contacts 318e, contacts 79a, now closed, contacts 140k, also closed, to line 91, through switch S23c. This relay controls the inverting contacts 156a, 156b associated with ACC#3 and causes an inverted reading to be taken at this time.

Since the units orders of sections I and II are initially in agreement, the relay magnet 323 is immediately energized and column shifting also takes place so that the inverted amount is entered in ten times its value and since the difference between the two dates is ten, but a single transfer cycle is required.

Following the transfer cycle, the machine enters upon the usual total taking and resetting

operation during which ACC#1, ACC#2, and ACC#6 are again zeroized.

These accumulators are conditioned to reset following a minor group change which in this case is a change in day number of successive cards, and the conditioning is effected by plug connecting the related zero button magnets 157 to sockets C-1 as explained under the heading "Zero button magnet circuits." The accumulators 3, 4 and 5 have their magnets 157 connected to socket C-2 for resetting on an intermediate change which in this case is a change in account number.

Last card of "interest period"

It may be explained that an X perforation is made in a selected column of the last card of each accounting period, which column in this case is the ninth column of the card for the 30th day. During the prior passage of the closing card past the upper brushes, at which time the day number 30 was read therefrom and entered into section II of ACC#6, the special perforation made in the X index point position of column 9 was analyzed by the upper brushes traversing the ninth column. This brush is plug connected as by plug connection 335 (see Fig. 10) to a plug socket 336. Upon sensing this X9 perforation, a circuit is completed which extends from upper brush UB traversing the ninth column, through plug connection 335 to socket 336 (L46), cam contacts T13, timed to close at X, upper card lever relay contacts UCLm, relay magnet 315 and in parallel therewith through relay magnet 337. Magnet 337 closes its contacts 337a which provide a holding circuit for the relay magnets through cam contacts T2 which maintain the circuit until the next following card feeding cycle. Relay magnet 315 opens its contacts 315d (C43) thereby disconnecting the adding magnets 25 of section I from the lower brushes so that during the next following cycle, the lower brushes will not effect an entry into section I. Energization of magnet 315 also closes its contacts 315d and, as explained, transfer cycles followed by a minor total taking cycle take place after the card for the 20th day has passed the lower brushes and the card for the 30th day with its X9 perforation has concurrently passed the upper brushes. During these transfer cycles the card feed is inactive and contacts T2 are closed to keep magnet 315 energized and its contacts 315d closed so that, when contacts SP19 close during the total taking cycle, a circuit is completed from line 90, switch S24, contacts SP19, 315d, magnet 340 to line 91. Magnet 340 closes its contacts 340a to establish a holding circuit from line 90, switch S24, contacts 341a, 340a, and magnet 340 to line 91. Since the controlling magnet 341 (L8) for contacts 341a is in the intermediate control circuit extending to socket C-2, this holding circuit will remain established until there is an intermediate group number change. Energization of relay magnet 315 causes closure of a pair of related contacts 315c (L47) which, if switch S24 is closed, will complete a circuit from line 90, switch S24, contacts 315c, relay magnet 338, to line 91. Magnet 338 closes its contacts 338a providing a holding circuit through cam contacts L23 until near the end of the cycle. Relay magnet 338 closes a further pair of contacts 338b (L45) which, if the card having the X9 perforation is the last card of the particular account number so that its passage by the lower brushes

caused a change in the intermediate group control set up, thereby closing contacts 103k (L45), a circuit would be completed as follows:

From line 90, contacts P1, contacts 338b, 103k, relay magnet 300, switch S23b, to line 91 so that upon sensing the last card of a group the machine will immediately enter upon total taking cycles of operation due to the immediate energization of relay magnet 300 thereby eliminating the heretofore intervening transfer cycles of operation.

Additional card

This circuit, in the consideration of the problem of Fig. 12, is not completed at this time since the additional transaction card which passes the upper brushes as the thirtieth day card passes the lower, does not permit a change in the intermediate group control section and only a minor group change is indicated between the date numbers 30 and 3 sensed by the lower and upper brushes respectively. As the thirtieth day card passes the lower brushes, the reading thereof will be suppressed, as explained, due to the open condition of relay contacts 315a (C43).

Since this thirtieth day card contains no amount perforations, there is no entry made into either ACC#1 or ACC#2 and the machine proceeds through the usual balancing cycle wherein nines are entered in the orders of ACC#3 and "1" carried into the units order, leaving the daily balance at 9954. During this initial transfer cycle for the card of the thirtieth day, the "primary" impulse circuit is completed under control of magnet 138 as before, and the lower double step relay 18 which was standing in its "odd" condition is changed to "even." However, the entry of the 9's has caused closure of contacts 160 of ACC#3 so that the resulting "secondary" impulse shifted relay 18 back to its "odd" condition. This balance is thereafter repeatedly transferred three times into ACC#5 while ones are entered into section I of ACC#6 in the manner already explained in detail above so that the amount standing on the accumulators will be as indicated on line 313 of Fig. 12. The machine then performs a total taking and resetting cycle of operations during which ACC#6 is zeroized and thereafter card feeding resumes to feed the additional card past the lower brushes.

Intermediate group change

This being the last card of the particular account, the next following card will bear a different account number, thereby causing a change in the intermediate group control mechanism and the incidental deenergization of intermediate control relay magnet 103 (L11). If this were the very last card in the hopper, the result would be the same for the reason that as this card passes the lower brushes, there would be no card passing the upper brushes and the upper card lever relay magnet UCL would be deenergized to open contacts UCLc (C10), so the holding circuits for the control magnets 97, 103 and 132 would be broken. Upon such deenergization, relay contacts 103p (L48) close, completing a circuit from line 90, switch S24, contacts 341a 340a, relay contacts 103p, relay magnet 318, to line 91. Magnet 318 is thus energized upon an intermediate group change, provided the circuit to magnet 340 has been initially established in response to an X9 perforation in a preceding card. The function of magnet 318 will be explained presently.

During the passage of this card by the lower brushes, the credit amount 70 is entered into ACC#2 and on the following cycle, this is again transferred in complementary form to ACC#3 and an extra one is carried into the units order, resulting in the complementary figure 9884. Here again just as for the preceding card, the double step relay 79 receives the two impulses to change it from "odd" to "even" and back again to "odd." The double step relay is now in "odd" condition and its function has heretofore been to convert the complementary balance in ACC#3 to its true number equivalent and enter the same in ACC#5. Under the present circumstances, however, the daily balance is transferred without inversion. This is taken care of in the following manner.

As previously explained, the inversion is brought about due to the energization of relay magnet 158 associated with ACC#3. The change in intermediate control, however, has caused opening of contacts 318e (L23) and closure of contacts 318f so that with double step relay contacts 79a closed due to its "odd" condition, a circuit may be completed through relay magnet 320 to associate ACC#3 with ACC#5 as explained, but relay magnet 158 is not energized since contacts 79c are open as well as contacts 318e. Therefore, during the three following transfer cycles, the complementary amount 9884 is transferred directly to ACC#5. For each transfer there is a mechanical carry operation involved from the highest to the lowest order so that the amount entered in each cycle is 9884 plus 1. Inspection of lines 312, 313 and 314 will show that the credit interest amount 450 is first increased by three times the amount of the daily balance as existing at the thirtieth day and is then reduced by three times such daily balance plus the additional credit amount, the net result being that the credit interest 450 is reduced by three times 70, resulting in a new credit interest figure of 240.

Entering 1 in section II of accumulator 6

The day number 3 from the last card is entered into section I of ACC#6 in the normal manner and entry of the day number from the next following card is suppressed because of the energization of magnet 318 which causes opening of the contacts 318a (L41) whereby the return circuit to the right side of the line is interrupted. The unit entering circuits are shifted from section I to II so that section II may be successively advanced to control the number of transfer cycles. This shifting of the entering circuits is effected as follows:

The energization of relay 318 will cause closure of contacts 318d (C41) and opening of contacts 318c whereby the unit entering circuit is disconnected from the units order magnet 25 of section I and connected to the units order magnet of section II. At the same time, contacts 318g (L41) are closed, completing the circuit to the left side of line 90. The circuit is thus traceable from line 91, socket M2, connection to socket L5, wire 331 to cam contacts L24, relay contacts LCLk, 300e, 323f, 318d, magnet 25, contacts 25a, contacts UCLp, switch S25, contacts 318g, to line 90. Upon agreement in the units orders of sections I and II, contacts 323g will close and if further stepping of these are required, the circuit will be directed through the tens order magnet 25 of section II and if, after the tens orders are in agreement, still further

stepping is required, the closure of contacts 326g will direct the circuits for energization of the hundreds order adding magnet 25 of section II. In the example of Fig. 12, after the three final transfer cycles, the machine automatically enters upon the total taking and reset cycle of operations during which total printing may be effected from ACC#3, ACC#4, and ACC#5, after which they are zeroized. With no new group following, both card lever relay magnets UCL and LCL would now be deenergized and contacts LCLc (C8) open so that there would be no automatic restarting of the machine and it would remain at rest. The circuit to plug socket C-2 (L8) which is completed in response to an intermediate group number change, includes relay magnet 341 whose energization during the resetting cycle will open its contacts 341a (L48) to permit deenergization of relay magnets 340 and 318.

Result printing

The selection of the total printing mechanism of ACC#4 and ACC#5 is effected through plug connections 342 (see Fig. 10) made between sockets C-6, C-7 and sockets D-3, D-6, and D-7. These circuits cause energization of the total print selecting relay magnets 149 in the printing banks in which these amounts are to be printed. The circuits include intermediate group control relay contacts 103m and the circuits are traceable from line 90, through relay contacts 320p or 320m accordingly as the double step relay is in "even" or "odd" condition, sockets C6 and C1, since switch S22c and contacts 103m are closed, and plug connections 342, to sockets D-3, D-6 and D-7 (R23), contacts 179a, now closed, relay magnets 149, switch S5 (R25), cam contacts SP12, line 91. In this manner, both figures are printed upon an intermediate group change. During minor total printing cycles, only the relay magnet 149 associated with socket C-6 is energized when the double step relay 320 is in "even" condition with contacts 320p closed and if the relay is in "odd" condition with contacts 320m closed, only relay magnets 149 connected to socket C-7 are energized. Near the end of the total printing cycle cam contacts SP13 (C22) close and, since the double step relay 79 is in "odd" condition, the relay is given a further resetting impulse to restore it to its normal "even" condition. This circuit includes contacts 79b, closed when the relay is set in "odd" condition, contacts 151a, closed by the zero button magnet related to ACC#3, and contacts 156c closed by magnet 156 (lower) which became energized when magnet 318 was deenergized and its contacts 318e closed to enable the circuit through magnet 156 to be completed.

In the example of Fig. 13, the same problem is presented as in Fig. 12 with the exception that the last card of the group represents a debit item instead of a credit item and it is assumed that preceding cards are the same as in Fig. 12 so that line 312 of Fig. 13 represents the same conditions as line 312 of Fig. 12.

Since there is no amount entry from the thirtieth day card, the balance of 45 in ACC#3 is entered three times in ACC#5 in the same manner as in Fig. 12 and ones are entered in section I of ACC#6 so that line 313 of Fig. 13 represents the same as the similarly numbered line of Fig. 12. The debit item 70 on the last card in this case is entered into ACC#3 and the resulting balance is a true number 24 which changes

the condition of the double step relay to "even" so that in the now familiar manner, ACC#3 is associated with ACC#4 and transferring will take place between these two accumulators. The change in account number will, as explained, cause energization of relay 318 with the resulting closing of contacts 318f (L23) so that relay magnet 156 becomes energized to effect an inversion of the amount transferred. Thus the repeated entries made into ACC#4 are of the number 9975. Each entry involves a highest order carry operation so that the actual entry in each cycle is 9975 plus one. The net result of the final card of the account has thus been to reduce the debit interest figure from 525 to 453 and to increase the credit interest figure from 450 to 585.

A further condition is presented in Fig. 15 where it is assumed as on line 350 that there is a positive balance of 100 in ACC#3 and debit and credit interest figures of 1215 and 645 respectively at the time of the analysis of the thirtieth day card. In this problem it is assumed that the last card bears a day number 13 and a debit amount 50. As before the day number 13 is entered into section II of ACC#6 and the balance 100 is transferred an amount equivalent to 13 times 100. The resulting figures are as on line 351.

Following the zeroizing of ACC#6 the amount 50 is entered from the last card into ACC#1 and ACC#3 and a new balance of 150 results in the latter accumulator. The double step relay now standing at "even" connects ACC#4 to receive the entry and the change in account number as in Fig. 13 causes energization of the related relay magnet 156 so that the amount is transferred in complementary form for the four transfer cycles, during each of which the highest order carry mechanism enters an additional one. The resulting debit interest figure is 565 which is the original figure 1215 reduced by 13 times 50. It is to be noted that during the last transfer cycle when the entry 9849 is shifted one place to the left that an additional nine must be entered in the units order to maintain the proper complementary value. This nine entry is effected in the following manner:

At (R43) is shown a pair of contacts 318h which close on the account number change. These contacts are connected through a wire 352 to the cam contacts SP9 (R27) and through relay contacts 300g and 140a to the contacts ZL9 so that at the nine time during transfer cycles, a circuit is completed from contacts ZL9 through relay contacts 140a, contacts 300g, wire 352, contacts 318h, through contacts 323h which close when there is comparison in the units orders of sections I and II and shifting of the entering circuit is effected. The circuit continues from contacts 323h through either contacts 320a or 326b to ACC#4 or ACC#5 as the case may be. If the day number discloses a difference in three orders, the circuit from contacts 318h will also continue through contacts 326h after the units and tens orders are in agreement to enter nine in the tens order of ACC#4 or ACC#5.

At (C41) are shown contacts 323i and 326i which serve to enter nines into the left hand orders of ACC#4 and ACC#5 when the size of the number entered is not equal to the capacity of the accumulator.

While there has been shown and described and pointed out the fundamental novel fea-

tures of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a machine of the class described, means for feeding record cards in succession, means for concurrently sensing a pair of successively fed record cards, a pair of accumulators, a pair of settable devices, means controlled by said sensing means for concurrently entering a different number into each of said devices, one number from each of the concurrently sensed record cards, further sensing means and means controlled thereby for entering an amount into one of said accumulators, means for repeatedly transferring the amount from said last named accumulator to the other accumulator, group control mechanism controlled by said first named sensing means, means controlled by said group control mechanism for interrupting operation of said card feeding means, further means controlled by said group control mechanism for initiating the repeated operations of said transferring mechanism, means operative during said transferring operations for advancing the settable devices containing the lesser number to raise the number therein to the value of the other number and means controlled by said settable devices when both are set at the same number for interrupting the operation of said transferring means.

2. In a machine of the class described, means for sensing record cards concurrently, each card containing a different amount designation, a pair of entry receiving devices, entering means for each, means controlled by said sensing means for controlling said entering means to enter an amount into each of said devices from two of said cards whereby each device contains a different number, resetting mechanism for both said devices, means for causing the entering means of the one of said devices containing the lesser number to repeatedly add ones to the initially entered lesser amount, means for comparing the entries in said devices and means controlled by said comparing means when the amounts are alike for initiating an operation of said resetting mechanism.

3. In a machine of the class described having a first sensing device and a second sensing device, means for feeding each of a succession of record cards to and past said devices in turn, each of which cards has designations thereon representing a different number, the cards being arranged in the ascending order of their numbers, said feeding means being arranged to feed the cards so that as one card is passing the second sensing device the next succeeding card concurrently passes the first sensing device, a pair of accumulators, transferring mechanism for causing the amount in one to be transferred to the other, group control means responsive to said sensing devices when two concurrently sensed cards contain different numbers, to cause interruption of the operation of said card feeding means after each of the two cards has passed its respective sensing device and to cause an operation of said transferring mechanism, and means for effecting repeated operation of said mechanism; in combination with a second pair

of accumulators, entering means therefor controlled by said sensing devices to enter in one the number on the card passing said first sensing device and in the other the number on the card concurrently passing the second sensing device, means for controlling the entering means of the accumulator containing the lesser number, to enter therein a unit for each transferring operation, resetting mechanism for said second pair of accumulators, means controlled by said second pair of accumulators when both contain the same number for interrupting the transferring and unit entering operations and for rendering said resetting mechanism effective to reset the accumulators and further means operative after resetting for rendering the card feeding means effective to advance the cards whereby numbers will be entered in the pair of accumulators from two cards, the lesser number of which will be that which was entered as the greater number during the prior sensing operations.

4. The invention set forth in claim 3 in which further sensing means is provided responsive to a special designation in one of the cards as said card passes the first sensing device, connection shifting devices for preventing the entry of a number from said second sensing device and means controlled by said further sensing means and rendered effective when said card having the special designation passes the second sensing device for rendering said shifting devices effective to prevent entry of the number on said card, whereby only the number on the succeeding card will be entered into its related accumulator.

5. In a machine of the class described, a balance accumulator, a credit accumulator, entering means for each, means for analyzing record cards for debit and credit amount representing designations, record controlled entry selecting means for selectively causing said entering means to be controlled by said analyzing means to enter debit amounts into said balance accumulator and credit amounts into said credit accumulator, group control mechanism responsive to group number designations on the cards, means including the entering means of the balance accumulator for transferring the amount standing in the credit accumulator to the balance accumulator in the form of a complement, means controlled by said group control mechanism for causing an operation of said transferring means, a credit interest accumulator, a debit interest accumulator, entering means for each, a second transferring means including the entering means of the credit interest accumulator and the entering means of the debit interest accumulator for transferring the amount in the balance accumulator to either of said debit interest or credit interest accumulators, means controlled in part by the balance accumulator for determining whether the amount in the balance accumulator is a complement, means controlled thereby for controlling the operation of said second transferring means to cause the amount in the balance accumulator to be transferred to either the debit interest or the credit interest accumulators, and means effective after the operation of said first transferring means for rendering the second transferring means effective.

6. In a machine of the class described having a pair of sensing devices for concurrently sensing a pair of record cards for designations representing any two different day numbers, one sensing device sensing the lesser number and the other sensing device sensing the greater number, a pair

of accumulators, one associated with each sensing device, entering means for each, said entering means being controlled by their related sensing devices to enter the day numbers, one in each 5 accumulator, means for controlling the entering means of the accumulator containing the lesser number to cause a unit to be entered therein to increase said lesser number by 1, a further pair of accumulators, transferring mechanism for 10 transferring an amount from one of said further pair of accumulators to the other, means operative after the day numbers have been entered for initiating and effecting repeated operation of said transferring mechanism, means for 15 causing an operation of said unit entry controlling means for each transferring operation, comparing means for determining whether the first named pair of accumulators contain the same number, means controlled by said comparing means when the first named pair of accumulators both contain the same number for 20 interrupting the transferring and unit entering operations, resetting means for each of said first named pair of accumulators and further means controlled by said comparing means when the first named accumulators both contain the same number for rendering said resetting means effective to reset said first named accumulators.

7. In a machine of the class described having a first sensing device and a second sensing device, means for feeding each of a succession of record cards to and past said devices in turn, each of which cards has designations thereon representing a different number, the cards being arranged in the ascending order of their numbers, said feeding means being arranged to feed the cards so that as one card is passing the second sensing device the next succeeding card concurrently passes the first sensing device, a pair of accumulators, transferring mechanism for causing the amount in one to be transferred to the other, group control means responsive to said sensing devices when two concurrently sensed cards contain different numbers to cause interruption of the operation of said card feeding means after each of the 30 two cards has passed its respective sensing device and to cause an operation of said transferring mechanism, and means for effecting repeated operation of said mechanism; in combination with a pair of settable devices, entering means therefor controlled by said sensing devices to enter in one device the number on the card passing said first sensing device and in the other the number on the card concurrently passing the second sensing device, means controlled by a part 35 of the first sensing device in response to the sensing of a special designation, on a card for suppressing the entry of a day number from such card into the related settable device from the second sensing device when said card passes the second sensing device whereby only the number on the card concurrently sensed by the first sensing device will be entered into the related settable device, means for controlling the entering means of the settable device containing the lesser number or no entry to enter therein a unit for each 40 transferring operation, resetting mechanism for said pair of settable devices, means controlled by said pair of settable devices when both contain the same number for interrupting the transferring and unit entering operations and for rendering said resetting mechanism effective to reset the settable devices and further means operative after resetting for rendering the card feeding 45 means effective to advance the cards whereby

numbers will be entered in the pair of settable devices from two cards, the lesser number of which will be that which was entered as the greater number during the prior sensing operations.

8. In a machine of the class described having a first sensing device, a second sensing device, means for feeding each of a succession of record cards comprising a group to and past said devices in turn so that as one card is passing the second sensing device the next succeeding card is passing the first sensing device, said cards containing minor and intermediate classification numbers, the card preceding the last card of the group containing a special designation, and group control mechanism comprising minor and intermediate sections controlled by said sensing devices and each section responsive to a change in its related classification in combination with a pair of accumulators, entering means for each, means for controlling said entering means to enter a unit in either accumulator, means controlled by said minor group control section for causing said unit entering control means to control the entering means of one of said accumulators and means controlled jointly by said intermediate group control section and part of said first sensing device upon sensing the special designation in the next to the last card of a group, for causing said unit entering control means to control the entering means of the other accumulator, means for determining when both accumulators contain the same number and means controlled by said determining means for rendering said unit entering means ineffective.

9. The invention set forth in claim 3 in which a card before the last card contains a special designation, means for sensing said designation and means controlled by said sensing means to suppress the entry of the day number for said card by the second sensing device whereby the number of units entered into the appropriate accumulator will equal the number entered by the first sensing device into the other accumulator.

10. In a record controlled tabulating machine, a pair of accumulators, an automatic group control mechanism responsive to minor and intermediate group number changes on record cards,

a device responsive to a special designation on a record card, transferring mechanism for transferring an amount from one of said accumulators to the other, means for conditioning said transferring means to transfer the amount additively or subtractively, means controlled in part by the transferring accumulator for selectively rendering said conditioning means normally effective to transfer in one of said manners, means controlled by said group control mechanism in response to a change in either a minor or intermediate group number for effecting an operation of the transferring means and means controlled jointly by said device and by said group control mechanism in response to an intermediate change for preventing the operation of the transferring means in the selected manner whereby an operation of the transferring means takes place in the manner other than said selected manner.

11. In a machine of the class described, means for feeding record cards in succession, means for sensing said cards, a pair of accumulators, a pair of settable devices, means controlled by part of said sensing means for entering a different number into each of said devices, one number from each of two successive cards, means controlled by another part of said sensing means for entering an amount into one of said accumulators, means for repeatedly transferring an amount from said last named accumulator to the other accumulator, group control mechanism controlled by a third part of said sensing means, means controlled by said group control mechanism for interrupting operation of said card feeding means, further means controlled by said group control mechanism for initiating the repeated operations of said transferring mechanism, means operative during said transferring operations for advancing the settable device containing the lesser number to raise the number therein to the value of the other number, a readout device for each settable device, comparing circuit connections between said readout devices, and means controlled by said circuit connections when both settable devices are set at the same number for interrupting the operation of said transferring means.
